[57] ABSTRACT

Apparatus for automatically stacking metal siding panels for packaging, with successive panels in the stack inverted and/or laterally offset relative to each other so that their formed longitudinal edges are interfitted,

and with protective sheets of paper interleaved between successive panels. The apparatus includes a conveyor for advancing the panels laterally, a plurality of heads with rotary arms movable into and out of a position for engaging and inverting panels advancing along the conveyor; rotatable stop members at the end of the conveyor for arresting an advancing panel in any selected one of a plurality of positions spaced slightly apart from each other, and a plurality of indexing arms for successively gripping each arrested panel by suction and advancing it a fixed distance to a stacking locality where the indexing arms deposit the panels in parallel superposed relation, so that successive panels in the stack are laterally offset in correspondence with the spacing between the positions in which they are respectively arrested by the stop members. Sheets of paper to be interleaved with the panels are successively supplied to, and held on, a vacuum table adjacent the stacking locality; a movable wand operating in synchronism with the indexing arms picks up a sheet from the vacuum table, conveys it to the stacking locality, and deposits it on the uppermost panel at that locality, i.e. between deposit of successive panels on the stack. Successive adherence of the paper to the vacuum table and the wand, and release of the paper from the table and the wand, are effected by the reversible application of suction and air blasts to the paper through the table and the wand. Means are also provided for depositing a completed stack of panels on a carton blank and folding the blank around the panels.

APPARATUS FOR STACKING PANELS OR THE LIKE

BACKGROUND OF THE INVENTION

This invention relates to apparatus for stacking and packaging extended flat articles such as metal panels or the like. In a specific sense, it is directed to apparatus for placing flexible sheet material, e.g., paper, between successive panels or like articles in a stack of the articles. In a further specific aspect, it is directed to apparatus for disposing successive panels or like articles in predetermined different positions relative to each other in a stack.

One important particular application of the invention, to which detailed reference will be made herein for purposes of illustration, is in the stacking and packaging of metal siding panels as used in building construction. has

A typical metal siding panel is an elongated strip e.g. fabricated of aluminum, as much as 12 feet in length and 8 inches or more in width, having channels, flanges and/or beads formed along its opposite longitudinal edges to enable interlocking of adjacent siding panels when the panels are mounted on a building wall. Commonly, the opposite formed longitudinal edges differ from each other in configuration, and project in respectively opposite directions from the major surface planes of the panel; additional longitudinally extending bends may be formed in the panel intermediate these formed edges, for functional and/or ornamental purposes. The exterior surface of each panel is usually painted or otherwise coated or finished by the manufacturer, so that the panels are ready to be mounted in assembled relation on a building wall without further painting or finishing.

In present-day practice, the prepainted panels, cut to size and having formed longitudinal edges as described, are stacked by the manufacturer for packaging in cartons, each of the cartons containing a single stack of ready-to-use panels. Long sheets of paper are interleaved between the panels in the stack to protect the paint or other coating on the panel surfaces from damage resulting from abrasion of adjacent panels. To minimize the space occupied by the stack, the panels are so placed in the stack that their respective longitudinal edges are disposed in more or less interfitting or nested relation; thus, successive panels may be inverted relative to each other, and also positioned with their formed longitudinal edges offset relative to each other, i.e. to provide optimum interfitting of edges of adjacent panels for spatial economy.

The particular stacking pattern employed is dependent on the specific shape of the panels being stacked. That is to say, the relative offsetting of successive panels, and also the sequence of inversion in the stack (i.e. whether alternate panels are inverted, or every third panel, every fourth panel, etc.) is determined by the configuration of the panels. In certain stacking patterns, wherein some of the panels are disposed in back-to-back relation, i.e. with unpainted surfaces facing each other, it may be desired for reasons of economy to omit the protective paper sheets between such panels and to place the interleaving sheets only adjacent painted panel surfaces; hence the interleaving sequence, as well as the inversion sequence, may be varied depending on panel shape.

Heretofore, the stacking of metal siding panels has been performed by hand, owing to the manipulative complexity of the operations required to achieve a properly edge-interfitted stack of panels, and also to the difficulty of handling the long interleaving sheets of paper. The pre-cut, formed and painted panels are delivered to a stacking station where a plurality of workers manually invert selected ones of the panels, stack them in the desired edge-offset relation, and place sheets of interleaving paper between them as the stack is built up. Thereafter a corrugated board carton blank is folded around the stack to complete the packaging operation. The necessity for manual stacking and packaging has added undesirably to the cost of labor and time required for production of siding.

SUMMARY OF THE INVENTION

An object of the present invention is to provide new and improved apparatus for stacking extended flat articles.

Another object is to provide such apparatus for interleaving sheets of flexible material such as paper between successive articles in the stack.

A further object is to provide such apparatus for placing successive articles in predetermined inverted and/or edge-offset relation to each other in a stack.

Yet another object is to provide such apparatus wherein the sequence of stacking, inverting, edge-offsetting and/or interleaving operations can be varied by presetting the apparatus to perform a particular desired sequence.

A still further object is to provide new and improved apparatus for fully automated stacking of metal siding panels or the like with successive panels positioned in relation to each other for optimum economy of space and with protective sheets of flexible material such as paper interleaved between adjacent panels.

To these and other ends, the present invention broadly contemplates the provision of panel-stacking apparatus including, in combination, means for successively advancing a plurality of elongated panels transversely of their length along a defined path to a first locality; means for inverting a panel advancing along the path ahead of the first locality by turning the panel about an axis parallel to its length, the inverting means being selectively operable to invert only certain ones of successively advancing panels in accordance with a predetermined sequence; means for arresting panels at the first locality at any one of a plurality of positions at which the panels are disposed at respectively different distances from a fixed line parallel to their length, the difference between any two of the aforementioned distances being less than the width of a panel, and the arresting means being selectively operable to arrest successively advancing panels at respectively different positions in accordance with a predetermined sequence; and means for successively transferring arrested panels from the first locality to a second locality and depositing the panels in superposed parallel relation to each other at the second locality to build up a stack of the panels while maintaining each panel in its orientation as arrested at the first locality. The panel-transferring means is adapted to remove each successive panel from the first locality after arrest thereof by the arresting means and prior to advance of the next successive panel to the first locality, and advances each panel the same predetermined fixed distance in a direction trans-

verse to its length in transferring the panel from the first locality to the second locality so that the relative positions of successive panels on the stack are determined by the respective positions at which they are arrested at the first locality.

The invention further contemplates, as a particular feature thereof, the provision of means for depositing an elongated sheet of flexible material (such as paper or the like) on, and in substantial alignment with, a panel deposited at the second locality, prior to delivery of the next successive panel to the second locality. In addition, there may be provided means for depositing, at a third locality, a carton blank shaped and dimensioned to be folded around a stack of the panels to laterally enclose the stack; means for transferring a stack of panels from the second locality to the third locality and depositing the stack on a carton blank at the third locality in position to be laterally enclosed thereby; and means for folding a carton blank laterally around a stack of panels at the third locality.

In specific embodiments of the invention, wherein the advancing means comprises a plurality of spaced parallel conveyor belts for advancing successive panels resting thereon, the panel-inverting means may include a plurality of heads respectively disposed intermediate the belts along a common line transverse to the path of panel advance and positionable in the path, and a corresponding plurality of arms respectively pivotally mounted on the heads for rotation about a common axis parallel to the last-mentioned line. The arms normally project from the heads in a common direction opposite to the direction of the path of the panels so as to underlie a panel advancing in the path to the heads. The inverting assembly also includes means for simultaneously rotating the arms upwardly through about 180° upon advance of a panel to the heads, when the heads are positioned in the path, such that the arms lift the panel above the belts and over the heads and return the panel to the belts beyond the heads while turning the panel through 180°, the rotating means thereupon effecting return rotation of the arms to their normal position; and means for raising the heads into a position in the path and lowering the heads downwardly below the path to permit passage of a panel along the path without inversion of the panel.

The panel-arresting means of the apparatus includes a plurality of identical stop members spaced along a fixed line parallel to the advancing panels for engaging spaced portions of a longitudinal edge of an advancing panel at the aforementioned first locality, each of the stop members having plural stop faces for engaging the panel edge; means supporting the stop members for rotation about parallel axes intersecting the last-mentioned fixed line, the plural stop faces of each stop member being disposed at respectively different radial distances from the axis of rotation of the stop member, and the corresponding stop faces of all the stop members having a common orientation; and means for rotating the stop members simultaneously through a common angular increment to bring first one and then another of the stop faces of each stop member into panel-edge-engaging position as successive panels are advanced to the first locality. Thereby, successive panels are arrested at different distances from the aforementioned fixed line, these different distances respectively corresponding to the different distances at which the stop faces are spaced from the axes of rotation of the

stop members. In a particular embodiment, each of the stop members has four stop faces spaced from the axis of rotation of the stop member by respectively different radial distances, adjacent ones of the stop faces being oriented at 90° to each other around the periphery of the stop member; the stop member rotating means effects simultaneous rotation of the stop members through angular increments of 90° to successively present different stop faces of the stop members in facing relation to advancing panels.

With the first (panel-arresting) and second (stacking) localities of the apparatus spaced apart horizontally in a direction transverse to the length of panels advancing in the aforementioned path, the panel-transferring means may comprise a plurality of identical transfer arms each including means at each end thereof for holding a portion of a panel, the holding means being operable to grip and to release a panel, and the arms being dimensioned to extend from the first locality to the second locality; means mounting the transfer arms at their midpoints for rotation about vertical axes spaced apart in a plane bisecting the distance between the first and second localities; and means for simultaneously indexing the transfer arms through 180° between rest positions in which the arms extend, parallel to each other, from the first locality to the second locality, with the holding means at opposite ends of the arms respectively disposed at the first locality and the second locality. The transfer arms, at each rest position, are simultaneously engageable with spaced portions of a panel arrested at the first locality, for gripping the spaced portions of the panel by the holding means then disposed at the first locality, such that subsequent indexing of the arms conveys the gripped panel to the second locality for release at the second locality by the last-mentioned holding means.

The means or assembly for interleaving sheets of flexible material between successive panels of the stack, in accordance with the invention, includes a table providing a surface for supporting a sheet of the flexible material in position for transfer to the stack, the surface having openings for gas flow therethrough; means for delivering a sheet onto the surface; and means for producing reversible gas flow through the openings to hold a sheet on the surface by suction and to lift a sheet from the surface, depending on the direction of the gas flow. For transferring a sheet from the table surface to the uppermost panel at the aforementioned second locality and depositing the sheet thereon, the interleaving assembly also includes an elongated member or wand; means for moving the elongated member, between a first position closely overlying the table surface and a second position overlying the second or panel-stacking locality, in synchronous relation with operation of the panel-transferring means such that the elongated member moves to and from its second position between delivery of successive panels to the stacking locality; and means for producing a reversible gas flow through the elongated member to cause a sheet to adhere to that member by suction and to release the sheet therewith depending on the direction of the gas flow. In addition, means are provided for controlling production and direction of gas flow through the table surface and the elongated member by the gas-flow-producing means respectively associated therewith, for transfer of a sheet from the table surface to the elongated member while that member is at its first position, for transport

of the sheet in adherence to the elongated member to the second position thereof, and for release of the sheet from the member at that second position.

Further features and advantages of the invention will be apparent from the detailed description hereinbelow set forth, together with the accompanying drawings.

BRIEF DESCRIPTION OF THE DRAWINGS

FIG. 1 is a fragmentary perspective end view of two identical metal siding panels of a type suitable for stacking by the apparatus of the present invention, showing the positions of the panels relative to each other in a stack of such panels;

FIG. 2 is an end elevational view of six panels of the type shown in FIG. 1, further illustrating the stacking pattern for these panels;

FIG. 3 is a simplified schematic plan view of panel-stacking apparatus embodying the present invention in a particular form;

FIG. 4 is a simplified schematic side elevational view of the apparatus of FIG. 2;

FIG. 5 is a fragmentary plan view of the structures for inverting and laterally positioning the panels, in the apparatus of FIGS. 3-4;

FIG. 6 is a side elevational view of the inverting and positioning structures taken along the line 6-6 of FIG. 5;

FIG. 7 is a fragmentary view similar to FIG. 6, illustrating the operation of the inverting structure;

FIG. 8 is an elevational view of the inverting structure, taken along the line 8-8 of FIG. 6;

FIG. 9 is an enlarged sectional elevational view of one head of the inverting structure of FIGS. 5-8;

FIG. 10 is an enlarged side elevational view of the transfer arm assembly, interleaving wand, and associated elements of the apparatus of FIGS. 3-4;

FIG. 11 is a plan view of the structures of FIG. 10, taken along the line 11-11 of FIG. 10;

FIG. 12 is an elevational view of the same structures, taken along the line 12-12 of FIG. 11;

FIG. 13 is an enlarged sectional elevational view of the transfer arm assembly taken along the line 13-13 of FIG. 12;

FIG. 14 is a further enlarged sectional elevational view of one of the transfer arms;

FIGS. 15a, 15b and 15c illustrate successive stages in transfer of a first panel from the pick-up locality to the stacking station of the apparatus of FIGS. 3-4;

FIGS. 15d, 15e, and 15f are views respectively corresponding to FIGS. 15a, 15b and 15c, illustrating successive stages in transfer of a second panel to a position immediately above the first panel at the stacking station;

FIG. 16 is an enlarged side elevational view, partly in section, of the stacking station, interleaving assembly, and associated elements of the apparatus of FIGS. 3-4;

FIG. 17 is a plan view of elements of the interleaving assembly;

FIG. 18 is an enlarged sectional view taken along the line 18-18 of FIG. 17;

FIG. 19 is an enlarged fragmentary sectional view taken along the line 19-19 of FIG. 18;

FIG. 20 is a further enlarged sectional view taken along the line 20-20 of FIG. 19;

FIG. 21 is an elevational view of the paper supply unit of the apparatus of FIGS. 3-4, taken along the line 21-21 of FIG. 19;

FIG. 22 is a side view of the paper supply unit, taken along the line 22-22 of FIG. 21;

FIG. 23 is an enlarged fragmentary plan view of the stacking station, taken along the line 23-23 of FIG. 16;

FIG. 24 is a fragmentary elevational view of the stacking station, taken along the line 24-24 of FIG. 16;

FIG. 25 is a fragmentary plan view of the stacking and packaging stations of the apparatus of FIGS. 3-4, taken along the line 25-25 of FIG. 16;

FIGS. 26 and 27 are fragmentary views, similar to FIG. 25, illustrating successive stages in the operation of the structures for transferring a stack of panels from the stacking station to the packaging station;

FIG. 28 is an elevational view of the packaging station illustrating the means for advancing carton blanks thereto;

FIGS. 29a, 29b, 29c, 29d, and 29e are schematic circuit diagrams of successive portions of a control system for the apparatus of FIGS. 3-4; and

FIGS. 30, 31, 32, 33, and 34 are end views of stacks of panels illustrating stacking patterns for various different panel configurations.

DETAILED DESCRIPTION

The invention will be described as embodied in apparatus for stacking and packaging metal (e.g. aluminum) siding panels with sheets of paper interleaved between the panels to protect the painted external surfaces thereof from damage caused by abrasion of adjacent panels in the packaged stack.

By way of specific example, one form of siding that may be stacked by the present apparatus is illustrated in FIGS. 1 and 2. Each piece of siding comprises an elongated aluminum panel 10, e.g. 8 inches wide and 12 feet 6 inches long, painted or otherwise protectively and/or decoratively coated on its exterior surface 11 prior to stacking and packaging. Although the major extent of each panel 10 is flat, its lower longitudinal edge is bent inwardly and upwardly to form a channel flange 12 extending for the full length of the panel, while an outwardly and downwardly projecting lip or bead 14 is formed adjacent the upper longitudinal edge 15 of the panel, again extending for the full length thereof. When the panels are mounted in parallel overlapping relation on a wall, one above another and with their painted surfaces facing outwardly, the lower edge channel flange 12 of each panel receives the upper edge lip 14 of the immediately subjacent panel so as to interlock the panels, in accordance with conventional practice.

The panels, with their edges formed, their outer surfaces painted, and precut to length, are delivered to a packaging station to be stacked and placed in cartons each containing one stack of e.g. 24 panels. It will be apparent that the panels cannot satisfactorily be stacked with their longitudinal edges aligned and having a common orientation, because the disposition of all the flanges 12 in superposed relation on one side of the stack, and all of the lips 14 in superposed relation on the other side of the stack, would render the stack unstable as well as excessively bulky. Accordingly, successive panels are placed on a stack 16 (FIG. 2) in in-

verted relation to each other and also in laterally staggered or offset relation to each other so that the adjacent formed longitudinal edges of successive panels are disposed in a more or less interfitting or nested arrangement permitting successive panels to lie flush with each other, thereby to enhance the stability of the stack and to minimize the space occupied by the stack.

In the specific stacking pattern shown in FIG. 2, a first panel 10a is placed with its exterior surface 11a facing upwardly and its flange 12a disposed to the right as seen in FIG. 2. The second panel 10b to be added to the stack 16 is inverted, i.e. its exterior surface faces downwardly (toward panel 10a) and its flange 12b is disposed to the left as seen in FIG. 2. Panel 10b overlies panel 10a in the stack and is parallel thereto, but its longitudinal edges 12b and 15b are offset to the right of the respectively subjacent edges 15a and 12a of panel 10a, by a distance d_1 sufficient to permit the major surfaces of panels 10a and 10b to lie flush without interference between lip 14a and flange 12b on the left, or between flange 12a and lip 14b on the right, as seen in FIG. 2; thus the flange 12b and lip 14a are disposed in a more or less interfitting or nested arrangement, as are the flange 12a and lip 14b.

The third panel 10c to be placed on the stack has the same orientation as panel 10a, i.e. its exterior painted surface 11c faces upwardly and its flange 12c is disposed to the right as seen in FIG. 2. It is deposited on the stack in parallel, overlying relation to the panel 10b, with its longitudinal edges 12c and 15c offset to the right (as seen in FIG. 2) of the adjacent longitudinal edges of panel 10b by a distance d_2 ; i.e. the longitudinal edges of panel 10c are displaced to the right of the longitudinal edges of panel 10a by a distance d_1+d_2 . The offset distance d_2 is sufficient to permit nesting or interfitting of the formed longitudinal edges of panels 10b and 10c so that, again, the major surfaces of panels 10b and 10c are flush.

The fourth panel 10d on the stack is inverted (i.e. oriented as panel 10b) and has its longitudinal edges offset by a distance d_3 to the right of the longitudinal edges of panel 10c, permitting the formed edges of panels 10c and 10d to interfit so that the major surfaces of these two panels are flush.

There is thus provided a stack of four panels all having major surfaces in flush, parallel relation to the adjacent panels, with a cumulative offset (between the longitudinal edges of panels 10a and 10d) equal to $d_1+d_2+d_3$. This four-panel stacking pattern is repeated for the next four panels in the stack. In other words, the fifth panel 10e has the same orientation as panel 10a and its longitudinal edges are directly above those of panel 10a, i.e. offset to the left of the edges of panel 10d (as seen in FIG. 2) by a distance equal to $d_1+d_2+d_3$; its major extent is spaced from the upper surface of panel 10d by the width of flanges 12d and 12e, which support panel 10e in parallel relation to the subjacent panels 10a-10d. The sixth panel 10f, inverted like panel 10b, is aligned with its longitudinal edges directly above those of panel 10b and offset to the right of the edges of panel 10e by distance d_1 . Subsequently added panels continue the stacking pattern, with a repeat cycle of four, until a stack of 24 (or any other desired number) of panels has been built up. The resultant stack is advantageously stable and compact, owing to the offset, interfitting arrangement of the formed longitudinal edges of adjacent panels and the fact that the

major surfaces of successive sets of four panels are parallel to each other.

To project the painted surfaces of the panels against damage caused by abrasion, long sheets 17 of paper or the like (comparable to the panels in length and width) are interleaved between successive panels as the stack is built up. A sheet 17 may thus be added to the stack after each panel is placed on the stack. However, for the sake of economy, the sheets of paper may (as shown) be omitted between those panels which have unpainted surfaces facing each other. For instance, a first sheet 17a is interleaved between the facing painted surfaces of panels 10a and 10b. No sheet is placed between panels 10b and 10c, because their facing surfaces are unpainted. A second sheet is placed between panels 10c and 10d; no sheet is placed between panels 10d and 10e; a third sheet 17c is placed between panels 10e and 10f, and so forth, i.e. a sheet of paper is added to the stack only after every second panel placed on the stack, since this is sufficient to protect the painted surfaces of all the panels.

The completed stack 16 of panels and interleaved paper sheets may be disposed on an elongated corrugated carton blank (not shown in FIG. 2) which may be folded and sealed or otherwise closed around the stack to package the stack for storage and/or shipment.

It will be understood that the stacking pattern shown in FIG. 2 is exemplary only, and that other stacking patterns (characterized by different sequences of inverting, offsetting and/or interleaving operations) may be used, dependent in particular on the specific configuration of the panels being stacked.

Heretofore, the sequence of stacking and interleaving steps described above has been performed by hand. The apparatus of the invention now to be described is designed to effect, fully automatically, the selective inversion, positioning and stacking of panels, interleaving of paper, delivery of the stack to a carton blank and folding of the blank, with provision for varying the sequences in performance of these steps as desired for particular panel configurations. Merely for purposes of illustration, the invention as embodied in the apparatus shown in FIGS. 3-27 will be described with detailed reference to stacking of panels in accordance with the stacking pattern shown in FIG. 2.

GENERAL ORGANIZATION OF THE APPARATUS

Referring to FIGS. 3 and 4, the embodiment of the invention there illustrated comprises apparatus, generally designated 18, for stacking aluminum siding panels 10 in the stacking pattern shown in FIG. 2, the apparatus being also capable of stacking panels of different configurations in other appropriate stacking patterns.

Siding panels 10 to be stacked are delivered to the apparatus 18 in precut, prepainted, edge-formed condition (e.g. from a roll-forming machine, not shown) by means of a conveyor shown schematically at 20, which advances successive panels longitudinally to a predetermined position at the inlet side of the apparatus 18. All the panels as thus delivered have a common initial orientation, e.g. they are all delivered with their painted side 11 facing upwardly, and their longitudinal flanged edges 12 disposed to the right as seen in FIGS. 3 and 4. An inspector may be stationed adjacent the conveyor 20 to remove defective panels, either manu-

ally or by suitable mechanical means (not shown), before they are transferred to the apparatus 18.

A plurality of swing arms 21 are pivotally mounted at spaced localities along the side of the conveyor 20 opposite to the apparatus 18, for effecting transfer of each panel 10 from the conveyor 20 to the apparatus 18 upon arrival of the panel at the desired locality for such transfer. Specifically, when a sensor or limit switch (not shown) in the path of advance of panels on the conveyor 20 is engaged by the leading edge of an advancing panel, it actuates the arms 21 to swing (by suitable means, not shown) across the conveyor. The arms 21 thus engage the longitudinal edge 15 of the panel and push or kick it laterally (to the right as seen in FIGS. 3 and 4, i.e. in a direction perpendicular to the long dimension of the panel) from conveyor 20 onto an upwardly sloping lateral conveyor 22 which is incorporated in the apparatus 18. This arrangement of conveyor 20 and arms 21 is generally similar to systems heretofore used for delivery of siding panels to a conventional manual panel-stacking and packaging station.

The conveyor 22 is the first of a succession of structures in the apparatus 18 that advance the panels 10 laterally (i.e. perpendicular to their long dimension), from left to right as seen in FIGS. 3 and 4, to deliver a stack of panels with interleaved paper to a carton blank (not shown in FIGS. 3 and 4) disposed on an outlet conveyor 24 on the right-hand side of the apparatus. Means shown as hinged arms 25 adjacent the outlet conveyor fold the carton blank around the stack of panels, and the packaged stack is then advanced longitudinally by the conveyor 24 to down-line stations for sealing and closing the ends of the carton.

Specifically, the conveyor 22 comprises a plurality of parallel, spaced, endless moving belts which advance each incoming siding panel laterally from the inlet conveyor 20 to a pick-up locality 28. A panel-inverting assembly 30 is disposed in the path of the advancing panels on the conveyor 22 and is operable to selectively invert desired panels in a sequence of advancing panels to provide a desired alternate or other inverted sequence of panels in a stack. A panel positioning assembly 32 disposed to engage the leading longitudinal edge of each advancing panel at the pick-up locality 28 establishes the relative lateral position of each panel in the stack to provide the desired laterally offset relationship of adjacent panels relative to each other in the stack.

At the pick-up locality, each panel is lifted by a plurality of rotatably mounted transfer arms 34 which swing the panel (from left to right as seen in FIGS. 3 and 4) to a stacking station 36, where a stack of panels is built up. An interleaving assembly 38, disposed to the right of the stacking station 36 and extending parallel thereto, delivers an elongated sheet of paper to the stack after each panel is deposited on the stack (or in such other sequential relation to the delivery of panels as may be desired) so that the panels in the stack are interleaved with paper as the stack is built up. Concurrently, a carton blank is disposed on the outlet conveyor 24, being delivered thereto from a stack or pallet of carton blanks by an overhead conveyor (not shown in FIGS. 3 and 4) disposed above conveyor 24. When the desired stack of siding panels with interleaved paper has been completed, it is delivered from the stacking station to the carton blank on conveyor 24 by

means of a stack transfer assembly 40, which moves the stack downwardly and to the right (as seen in FIG. 4) for deposit on the carton blank.

PANEL-INVERTING ASSEMBLY

As best seen in FIGS. 5-8, the lateral conveyor 22 comprises four endless belts 42 which extend, in spaced parallel relation to each other, over drive rollers 44 adjacent the conveyor 20 and over guide rollers 46 at the extremity of conveyor 22 remote from conveyor 20. The drive rollers 44 are mounted on an axially horizontal common drive shaft 48 which is journaled in brackets 49 supported by fixed rigid metal frame structure 50, and is connected to suitable conventional means (not shown) for continuously driving the four belts 42 in such direction that the upper runs 42a of the belts move from the drive rollers 44 to the guide rollers 46, i.e. away from the conveyor 20, at a common velocity. The guide rollers 46 are individually rotatably mounted in brackets 52 supported by other portions of the frame structure 50; they are aligned along a common horizontal axis which is parallel to, spaced horizontally from, and elevated above the axis of the drive shafts 48, so that the upper surfaces of the upper runs of belts 42 slope generally upwardly away from the conveyor 20.

The frame structure 50 further includes four transverse hollow guide members 54, respectively aligned with the four belts 42, and extending from a locality adjacent the drive shaft 48 to a locality adjacent the axis of guide rollers 46. Each of these guide members has a flat upper surface 55 along which the upper run of its associated belt 42 moves, the lower run of the belt passing through the interior of the guide member. The surfaces 55 slope gradually upwardly away from the drive rollers 44 in a common plane until they intersect a horizontal plane above and substantially tangent to the guide rollers 46, and then extend toward the rollers 46 in the latter horizontal plane. Thus the upper runs of the belts 42, guided on surfaces 55, advance first slopingly upwardly and then horizontally as they move toward rollers 46; the extent of the horizontal portions of the surfaces 55 adjacent rollers 46 (and the corresponding extent of the horizontal portions of the upper runs of belts 42), in the direction of belt advance, is at least somewhat greater than the width of a panel 10. Additional axially horizontal guide rollers 56 may be mounted within the guide members 54 at the locality at which the surfaces 55 become horizontal, for tangential engagement with the upper runs of the belts 42.

The guide members serve both to define the paths of advance of the belts, and to aid in supporting the panels 10 being carried by the belts from the conveyor 20 to the pickup locality 28. Each panel 10 is deposited, by the action of swing arms 21, on the upper surfaces of the upper runs of belts 42 adjacent the drive rollers 44, with the painted surface 11 of the panel facing upwardly and the flange 12 oriented to the right as seen in FIG. 6; the long dimension of the panel extends transversely of the four belts 42 so that the panel is advanced by the belts in a direction perpendicular to its long dimension, the longitudinal flange 12 being the leading edge of the advancing panel. The rate of delivery of the panels 10 to the apparatus 18 by the conveyor 20 is such that successive advancing panels are spaced widely apart on the belts 42, i.e. by a distance

at least substantially greater than the width of a panel.

The panel-inverting assembly of the present invention (best seen in FIGS. 5-9) is operable to intercept an advancing panel on conveyor 22 at a locality 57 intermediate the drive rollers 44 and the pick-up locality 28, and to turn the panel about an axis parallel to the long dimension of the panel so that, beyond locality 57, its painted surface 11 faces downwardly and its longitudinal edge 15 (opposite to flange 12) becomes the leading edge of the advancing panel. This assembly is also operable to permit advance of a panel through locality 57 without inversion; i.e. assembly 30 is adapted to provide selective inversion of alternate ones of a succession of advancing panels, or other inversion sequences, as may be desired for particular stacking patterns.

The assembly 30 includes a rigid frame 58 disposed directly beneath conveyor 22 for movement relative thereto in a substantially vertical direction. The frame 58 is supported by a pair of elongated arms 60 extending forwardly (i.e. in the direction of advance of the panels) from the frame to pivotal mountings 61, which secure the arms to the conveyor frame structure 50 for angular movement of the arms about a horizontal axis transverse to the belts 42. In addition, the frame 58 is supported by a fixedly mounted hydraulic lift mechanism 63 disposed beneath and pivotally connected to the frame. The lift mechanism, which may in itself be a conventional hydraulic lift, is operable to raise and lower frame 58 as hereinafter further explained.

Specifically, frame 58 comprises an elongated, rigid, hollow horizontal member 64 extending transversely of the belts 42 beneath the guide members 54, and three rigid, hollow vertical members 66 mounted in spaced relation to each other on member 64 and projecting upwardly therefrom in the spaces between adjacent belts 42 of the conveyor 22. The upper extremity of each vertical member 66 is rounded about a horizontal axis of curvature transverse to the belts to constitute a head 68. When frame 58 is lifted to the upper limit of its vertical travel by mechanism 63, the three heads 68 project above the plane of the upper run of belts 42, as shown in FIG. 7, and in broken lines in FIG. 8; downward movement of the frame 58, on the other hand, retracts the heads 68 to a level below the upper run of belts 42, as shown in FIG. 6, and in solid lines in FIG. 8.

Three identical L-shaped arms 70 are respectively mounted on, and carried with, the three heads 68 for rotation about a common horizontal axis that extends transversely of the belts 42. As shown, this axis intersects the short limb 70a of each arm 70, and is elevated above the upper run of belts 42 when the heads are fully raised.

At rest, each arm 70 is disposed with its short limb projecting downwardly from the last-mentioned axis and its long limb 70b extending from the lower end of the short limb toward the drive rollers 44 in subjacent parallel relation to the plane of the upper run of belts 42. The arms 70 are entirely below the latter plane when the heads 68 are retracted. Even when the heads 68 are fully raised, these long limbs 70b are (as shown in FIG. 7) disposed, at the rest position, slightly below the level of the upper runs of belts 42, while the short limbs project upwardly into the path of advance of panels 10 on conveyor 22, so as to engage spaced points along the leading edge of an advancing panel, for arrest

of the panel at the locality 57. The long limbs 70b of the arms 70 then immediately underlie the arrested panel.

Means are provided for simultaneously indexing the arms 70 (about their common horizontal axis) upwardly and in the direction of panel advance, i.e. clockwise from the solid-line position to the broken line position shown in FIG. 7, through about 180°. With the heads 68 fully raised, and a panel 10 advanced into abutting relation to the short limbs 70a of arms 70, this indexing causes the long limbs 70b of the arms to lift the panel 10 upwardly off the belts 42, swing it over the heads 68 (with the panel flange 12 resting on the short limbs 70a), and return it to the belts 42 in an inverted position beyond locality 57 for continued advance on conveyor 22 to the pick-up locality 28. The panel (as shown at 10' in broken lines in FIG. 7) now rests painted side down on the belts 42, and its longitudinal edge 15 has become its leading edge. Upon completion of this 180° indexing motion, the arms 70 are indexed in reverse direction (i.e. counterclockwise in FIG. 7), back to the rest position.

The means for effecting rotation of the arms includes a drive shaft 72 journaled within the horizontal frame member 64 and connected through a flexible coupling 74 to a suitable and e.g. conventional indexing drive 75. Belts 76 extending vertically through members 66 connect the drive shaft 72 to the individual arms 70 for transmission of rotary drive thereto.

Operation of the described panel-inverting assembly is controlled automatically, in accordance with a preset inversion sequence, by a control system incorporating suitable switches and sensors (hereinafter described). Assuming that it is desired to invert every second panel in a succession of identical panels 10 delivered to the apparatus 18 by conveyor 20, the frame 58 may be initially in the retracted position shown in FIG. 6, with the heads 68 disposed below and out of the path of panel advance, so that the first panel 10 delivered to conveyor 22 is advanced through and beyond locality 57 by the belts 42 without being obstructed or inverted. A limit switch of the control system (hereinafter described), sensing and responding to the passage of this first panel, actuates the hydraulic lift mechanism 63 (through the control system) to elevate the frame 58 to the raised position shown in FIG. 7, i.e. raising heads 68 into the path of panel advance at locality 57.

As the second panel 10 advanced by belts 42 reaches locality 57, it trips a limit switch (hereinafter described) that actuates drive means 75 to simultaneously index the arms 70 clockwise from their rest positions. The arms lift the panel off the belt 42, turn it above the heads 68 through a 180° angle, and redeposit it on the belts 42 beyond the locality 57 (for continued advance to the pick-up locality 28) in an orientation which is inverted with respect to the initial orientation of the panel as delivered to conveyor 20. A further limit switch responds to completion of the inverting operation by actuating drive means 75 to reversely index the arms 70, for return of the arms to their rest position. Since the three arms 70 lift the panel at widely spaced points along its length, the inverted panel as returned to belts 42 remains properly aligned, i.e. with its long dimension perpendicular to the direction of advance of belts 42. In response to the advance of this second panel, a limit switch actuates the hydraulic lift mechanism (through the aforementioned control system) to

retract the frame 58 again to the position shown in FIG. 6, and thereby to permit the third delivered panel to advance through the locality 57 without being inverted.

The described sequence of panel-inverting operations is performed entirely automatically, by the pre-set control system which responds to advance of successive panels to alternately raise and lower the frame 58 and to index the arms 70 when the frame is in raised position. The control system is actuated only by panels that have been transferred to, and are advancing on, the conveyor 22, so that the panel-inverting assembly does not respond to panels, delivered by conveyor 29, that may be removed as defective before transfer to conveyor 22.

In this way, each successive panel 10 advancing beyond locality 57 on conveyor 22 is inverted in orientation relative to the immediately preceding and following panels, and this sequence is maintained as long as panels continue to be delivered to the conveyor 22 and the setting of the control system remains unchanged. The rate of delivery of panels 10 to conveyor 22 is such as to permit adequate spacing between successive panels for unimpeded operation of the inverting assembly. By appropriately resetting the control system, the inverting assembly may be operated to invert two successive panels and then pass two panels without inversion, as an alternative sequence of inversion.

PANEL-POSITIONING ASSEMBLY

As already described, beyond the inverting locality 57, the upper runs of belts 42 advance along horizontal portions of the guide member surfaces 55, which thus provide a horizontal support for the panels at the pick-up locality 28. Successive panels delivered to the latter locality by the belts 42 are, as stated, inverted relative to each other; but they are all substantially aligned with their longitudinal edges extending perpendicular to the direction of advance of the belts 42.

The panel-positioning assembly 32 of the apparatus 18 comprises a pair of stop members 80 disposed in spaced relation to each other at the pick-up locality 28 to engage widely spaced portions of the leading edge of an advancing panel 10 at that locality. These two stop members are identical in configuration, and are mounted for rotation about vertical axes which are fixed in relation to conveyor 22 and are disposed along a fixed horizontal reference line L parallel to the longitudinal edges of a panel being advanced by the belts 42 to locality 28.

As best seen in FIGS. 5 and 6, each of the stop members has four flat vertical stop faces 80a, 80b, 80c and 80d, disposed around the periphery of the stop member with faces 80a and 80b lying in perpendicular vertical planes, and faces 80c and 80d respectively parallel to faces 80a and 80b. Each of these faces is adapted to abut the leading edge of an advancing panel 10 when the member 80 is appropriately oriented, a different face being presented to the advancing panels each time the member 80 is indexed through 90°.

The four stop faces 80a, 80b, 80c and 80d are located at different (and progressively lesser) radial distances from the axis of rotation of the member 80. As stated, the two members 80 are identical; and they are so disposed and linked for indexing that the corresponding stop faces of the two members 80 are always oriented in a common direction. When the faces 80a are pres-

ented to a panel 10 advancing from left to right (as seen in FIG. 5) on the belts 42, they engage the leading longitudinal edge of the panel to arrest the panel at a position (at pick-up locality 28) at which its leading edge is spaced to the left of the fixed reference line L by a distance d_a equal to the radial distance of the faces 80a from the rotational axes of the members 80; the panel then remains arrested in that position until it is picked up by the transfer arms 24, although the belts 42 continue to advance beneath it. However, means (including an appropriately positioned limit switch, hereinafter described) may be provided for momentarily halting the belts 42 until the arrested panel is picked up, thereby to avoid abrasion of the panel by the belts.

If the members 80 are indexed counterclockwise (as seen in FIG. 5) in successive 90° increments, so that succeeding panels are respectively stopped by stop faces 80b, 80c, and 80d, the leading edges of these succeeding panels are respectively halted at progressively lesser distances d_b , d_c , and d_d to the left of the fixed line L. In other words, stated with reference to the terminal or arrested position of the leading longitudinal edge of each panel at locality 28, the position of the edge of the second panel is offset by a distance d_a-d_b to the right of the position of the edge of the first panel; the third is offset by a further distance d_b-d_c to the right of the second; and the fourth is offset still further by a distance d_c-d_d to the right of the third, all as seen in FIG. 5. As will be understood, each panel arrested by the members 80 is picked up by the transfer arms 24 (hereinafter described) before the next panel reaches the pick-up locality on conveyor 22.

Thus, by virtue of the different radial positions of the four stop faces on each member 80, indexing of the members 80 causes the leading edges of successive advancing panels to be stopped at different though parallel positions relative to the fixed reference line L at the pick-up locality 28. These positions correspond to the desired offset positions of successive panels on a stack. For example, referring to the stack of panels shown in FIG. 2 and described above, the members 80 may be so dimensioned that the distances d_a-d_b , d_b-d_c , and d_c-d_d are respectively equal to the offset distances d_1 , d_2 , and d_3 in the stack. In other words, then, panel-inverting assembly 30 establishes the desired (face-up or inverted) orientation of successive panels for a stack, while the stop members 80 in cooperation with the belts 42 establish the desired relatively offset position of the leading edges of successive panels for a stack, by arresting the successive panels with their leading edges at predetermined different relative distances from a fixed reference line.

The members 80, mounted on vertical shafts 82 journalled in bearings 84 secured to the frame structure 50, are indexed together by suitable drive means (not shown) through a common shaft 86. The extent of each indexing movement of each member 80 is determined by means of an appropriately shaped cam 88 mounted on the shaft 82 and cooperating with a pivotally mounted cam follower 90 also supported by the frame structure 50. The drive means for the members 80 is operated automatically through the aforementioned control system, e.g. in response to removal of each panel from the pick-up locality, to effect the requisite indexing of the members 80 for arresting the next succeeding panel in a desired position for a predetermined stacking pattern. While operation providing the pattern

of FIG. 2 is described above, i.e. with successive 90° counterclockwise indexing motions of the members 80 to position the leading edge of each of four successive panels progressively closer to line L, it will be understood that other indexing sequences may be provided for the members 80 (to produce a different succession of relatively offset positions for successive panels) by replacing the illustrated positioning cams 88 with other positioning cams.

The described positioning assembly may further include an end stop mechanism 94 (FIG. 8) disposed to engage one end of each advancing panel 10 as the panel reaches the pick-up locality 28, for ensuring that the ends of every panel are aligned along a fixed common line (perpendicular to line L) before the panel is engaged by the transfer arms. This mechanism 94 includes a head 96 for engaging the end of a panel, and means 97 for reciprocating the head in a direction parallel to the long dimension of the panel. The reciprocating means 94 is actuated through the control system, in response to arrival of a panel at locality 28, to advance the head 96 for engaging the adjacent panel end to displace the panel longitudinally into the desired aligned position. Means 97 then automatically retracts the head until the next panel is delivered to locality 28.

TRANSFER ARMS

Three identical transfer arms 34 (shown in FIGS. 10-14) are included in the apparatus 18. They are mounted for rotation about vertical axes lying in a common plane that is parallel to the fixed line L (FIG. 5) and midway between the pickup locality 28 and the stacking station 36, which is spaced to the right of locality 28 as seen in FIGS. 3, 4, and 10. The stack transfer assembly 40 (hereinafter further described) provides a platform at the station 36 for supporting a stack of the panels 10 in parallel relation to the position of the panels at the pick-up locality 28. The function of the transfer arms is to advance the panels from locality 28 to station 36, i.e. from left to right as seen in FIG. 10, and to deposit them at the stacking station so as to build up a stack of the panels on the aforementioned platform.

Each transfer arm comprises a hollow, rigid horizontal member 100 suspended at its midpoint on a vertical shaft 102 for rotation about the shaft axis and also for vertical movement; the members 100 are disposed above the level of pick-up locality 28 and stacking station 36, and are sufficiently long to extend across the full width of the space between locality 28 and station 36. The shafts 102 of the three transfer arms 34 extend upwardly through a housing 104 (FIGS. 11-13) fixedly mounted above the transfer arms.

Each shaft 102 includes a central, axially vertical, non-rotating rod 106, which extends upwardly from the member 100 through and above the housing 104, and which is vertically reciprocable for raising and lowering the member 100. The rods 106 of the three transfer arms are individually connected at their upper ends, through linkage 108 (FIG. 13) to an axially horizontal rocker shaft 110 (FIGS. 11 and 12) journaled in supports 112 on the top of the housing 104. A drive 114, also mounted on the top of housing 104, indexes shaft 110 back and forth through an angle sufficient to impart vertical reciprocatory motion to the rods 106 (i.e. through the linkages 108) for raising and lowering the

members 100 between the solid and broken line positions shown in FIG. 13.

As best seen in FIG. 14, each rod 106 is connected to its associated horizontal member 100 by a bearing 116 (mounted in member 100) that permits rotation of member 100 relative to rod 106. Each shaft 102 further includes a hollow spline shaft 118, fixedly secured at its lower end to the member 100 and extending upwardly therefrom (in surrounding, spaced, concentric relation to the rod 106) to and through a spline fitting 120, so that the shaft 118 rotates with fitting 120 but is axially (i.e. vertically) movable relative to fitting 120. The fitting 120 of each transfer arm is carried in the lower end of an axially vertical hollow sleeve 124 which is rotatably mounted in bearings 126 in the housing 104 in concentric surrounding relation to the rod 106 of the same transfer arm, separate fittings 120 and sleeves 124 being provided for the three transfer arms. The central one of these sleeves 124 (designated 124a) bears a pulley 128 connected by means of a drive belt 130 (FIG. 13) to a suitable indexing drive 132 (mounted on the housing) for effecting precisely 180° of rotation of sleeve 124a in either direction. This drive is transmitted from the central sleeve 124a to each of the other sleeves 124 by means including a two-belt pulley 134 secured to sleeve 124a, pulleys 136 respectively secured to the two other sleeves 124, and two belts 138 respectively connecting the pulley 134 to the two pulleys 136, so that the drive 132 simultaneously indexes all three sleeves 124 in the same direction through precisely 180°. Thereby, the three horizontal members 100 are simultaneously indexed 180° in the same direction, since rotary motion of the sleeves 124 is positively transmitted to the members 100 by fittings 120 and spline shafts 118. The three members 100 have a common angular orientation at all times, and at rest they extend (parallel to each other) in a direction perpendicular to reference line L of FIG. 5, i.e. transversely between the pickup locality 28 and stacking station 36; hence each 180° indexing motion of the members 100 carries one end of each member 100 from a position directly above locality 28 to a position directly above station 36, and carries the other end of each member 100 in the reverse direction.

Each member 100 carries a pair of pick-up devices 140 respectively disposed at opposite ends of the member, equidistant from the axis of rotation of the member, so as to be respectively positioned directly above pick-up locality 28 and directly above stacking station 36 when the member 100 is in the above-described rest position. As best seen in FIG. 14, each device 140 includes a suction head 141 comprising a short horizontal bar 152 which bears, on its lower surface, two horizontally spaced suction cups 144 positioned to engage the upper surface of a subjacent panel 10. The bar is suspended at its midpoint (equidistantly from two suction cups) by a vertical spline shaft 146 for rotation relative to member 100 about a vertical axis and also for vertical movement relative to member 100. The spline shaft 146 of each device 140 is keyed in a spline fitting 148 which is rotatably supported in an end housing portion 150 of the member 100, so that shaft 146 rotates with fitting 148 but is vertically movable relative thereto. At its upper end (above fitting 148) each shaft 146 is rotatably mounted in a cup 152 carried on the lower end of the piston rod 154 of a pneumatic or hydraulic lift mechanism 156 mounted on housing portion 150. The

mechanism 156 raises and lowers the shaft 146 (and the suction head 141) relative to member 100 while permitting the shaft to rotate.

The lower end of each rod 106, within its associated member 100, bears a two-belt pulley 158 respectively connected by a pair of belts 160 to the two fittings 148 at opposite ends of the member 100. When the member 100 is indexed, the rod 106 remains angularly stationary while the ends of member 100 rotate through 180°; this relative angular movement between the pulley 158 and the member 100 (transmitted through belts 160) causes the fittings 148, shafts 146 and bars 142 to turn progressively in relation to the member 100, in such manner that the angular orientation of the bars 142 in relation to a fixed reference (e.g. line L of FIG. 5) remains unchanged throughout the indexing movement of the member 100.

The suction cups 144 are connected through flexible conduits to a suitable vacuum source, e.g. of generally conventional character, for selectively applying and removing suction; for simplicity of illustration, the conduits and vacuum source are not shown. Further flexible conduits (also not shown) supply fluid to the mechanisms 156 for raising and lowering the suction heads.

The heads 141 are shown as so oriented that the two suction cups 144 of each head are aligned in a direction perpendicular to the long dimension of the panels 10 at locality 28. However, they are adjustable to other orientations as may be desired e.g. for optimum engagement of the suction cups with panel surfaces of various different configurations.

The operation of the transfer arms may now be readily understood. With the arms at rest position, one suction head 141 of each of the three arms is disposed directly above the pick-up locality 28. When a panel 10 reaches locality 28, and is stopped by members 80 and aligned by mechanism 94, the three members 100 are lowered by drive 114, and the three last-mentioned suction heads 141 are also lowered by mechanism 156, to bring the suction cups 144 of these three heads into engagement with the upwardly facing surface of the panel. The bars 142 of heads 141 are so oriented that the two cups 144 of each head 141 engage the panel surface at points spaced along a line transverse to the long dimension of the panel, while the three heads themselves are relatively widely spaced along the long dimension of the panel; hence the panel is engaged by suction cups 144 at plural localities distributed over its surface, as desired for stability during transfer.

Suction is applied to the panel-engaging cups 144, causing the cups to grip and hold the panel surface. The horizontal members 100 are raised by drive 114, lifting the panel from the pick-up locality and elevating it sufficiently to clear the stop members 80. The heads 141 holding the panel remain in their lower position, but the free heads 141 at the opposite ends of the members 100 are raised by mechanisms 156 so as to clear the panel.

The three transfer arms are then simultaneously indexed 180° by drive 132, in a common direction, swinging the panel (from left to right in FIGS. 3, 4 and 10) over to a position immediately above the stacking station 36. Throughout this swinging motion, the panel-engaging suction cups remain adhered to fixed positions on the panel, as permitted by the above-described rotation of bars 142 relative to members 100, while the

raised free heads 141 at the opposite ends of the members 100 pass above the panel. The net horizontal displacement of the panel effected by this indexing of the transfer arms, in a direction perpendicular to the longitudinal edges of the panel (i.e. from left to right in FIGS. 3, 4 and 10), is a fixed distance equal to the diameter of the rotary path of any one of the suction cups 144.

After completion of the 180° indexing movement, the three members 100 are simultaneously lowered by drive 114, and suction is then removed from the panel-engaging cups 144, to release and deposit the panel on the platform at the stacking station 36. The panel as thus deposited is disposed in a position parallel to its previous position at locality 28, but spaced horizontally therefrom (in a direction perpendicular to its longitudinal edges) by the aforementioned fixed distance.

The free heads 141 of the three arms are now positioned directly above the pick-up locality 28. Upon arrival of the next panel 10 at that locality, these heads are lowered to bring their suction cups 144 into engagement with the panel surface, and suction is applied thereto, while the heads 141 above the stacking station are raised; the three transfer arms are then raised, and indexed 180°, to transfer this next panel to the stacking station.

The indexing, raising, lowering, suction-applying and suction-removing operations of transfer arms 34 are performed automatically through the control system hereinafter described, in response to the presence of a panel 10 in position for pick-up at locality 28, so that each 180° indexing of the arms 34 transports a properly positioned panel.

The position of one of the arms 34 and its heads 141 as one panel is deposited at the stacking station, and before pick-up of the next panel at locality 28, is shown in FIG. 10. In this view, the member 100 is illustrated in its lower position, and the head 141 above the stacking station is also in lower position, while the other head 141 (above the pickup locality) is in raised position. FIG. 12 shows the rest positions of the arms 34 in solid lines, and indicates by broken lines 34' their positions halfway through the indexing cycle. In each of FIGS. 13 and 14, the left-hand head 141 is shown as raised and the right-hand head 141 is shown as lowered; FIG. 13 also shows the lower (solid lines) and upper (broken lines) positions of the member 100.

Since the transfer arms do not alter the panel orientation (i.e. painted side up, or inverted), the orientation of the panels as placed on the stack at station 36 is that which is determined by the operation of the inverting assembly 30 as described above. Moreover, since the transfer arms advance each successive panel by the same fixed horizontal distance in moving it from locality 28 to station 36, the relative lateral positions of the successive panels placed on the stack at station 36 are determined by their respective positions relative to line L at locality 28, i.e. as established by the members 80. In other words, if a first panel 10 is stopped by members 80 at a distance d_a from line L in FIG. 5, and (after transfer of that panel by arms 34 to the stacking station) a second panel 10 is stopped by members 80 at a lesser distance d_b from line L, the second panel will be placed by the transfer arms on the first panel with its longitudinal edges offset to the right of the longitudinal edges of the first panel by a distance equal to $d_a - d_b$.

This operation may be further understood by reference to FIGS. 15a-15f, which illustrate in schematic plan view the successive transfer of two panels 10A and 10B by arms 34 from locality 28 to station 36. FIG. 15a shows panel 10A being picked up at locality 28 by the cups of heads 141A at one end of the transfer arms 34. The position of the leading edge of panel 10A (distance d_a from line L at locality 28) is established by the orientation of members 80. FIG. 15b shows panel 10A being advanced by the transfer arm. FIG. 15c shows the same panel being deposited on the platform at station 36. As shown, the position of the cups of heads 141A relative to the leading longitudinal edge 12A of panel 10A remains unchanged throughout the indexing cycle so that the position of edge 12A as delivered to station 36 is determined by (and a fixed horizontal distance D to the right of) the position d_a of that edge at locality 28.

During the foregoing indexing cycle, the members 80 are rotated to establish a different lateral position d_b for the leading longitudinal edge 15A of the second panel 10B to reach locality 28. As heads 141a deliver panel 10A to station 36, the heads 141b at the opposite ends of the transfer arms 34 come into position to pick up panel 10B at locality 28, as shown in FIG. 15d; panel 10B, it may be noted, has been inverted in orientation relative to panel 10A by the inverting assembly 30 (not shown in FIGS. 15a-15f) prior to reaching locality 28. Heads 141b now pick up panel 10B and the arms 34 index through 180° as shown in FIG. 15e, to deliver this panel 10B to the stack at station 36, as shown in FIG. 15f, the panel 10B being deposited on and parallel to panel 10A. Since panel 10B has been displaced to the right of its initial position by the same fixed distance D as panel 10A, the longitudinal edges of panel 10B as deposited at station 36 are offset to the right of the subjacent edges of panel 10A by a distance d_1 equal to the distance ($d_a - d_b$) between the respective positions of the panel leading edges 12A and 15B at locality 28.

In this way, i.e. through the cooperation of the inverting assembly 30, stop members 80, and transfer arms 34, a stack of panels is progressively built up on the platform at station 36 in a preselected relatively inverted and laterally offset disposition, e.g. to provide the stacking pattern of FIG. 2 or other desired stacking patterns. Buildup of the stack continues until a predetermined number of panels have been stacked.

INTERLEAVING ASSEMBLY

The interleaving assembly 38, for placing elongated sheets of paper 17 between successive panels 10 in the stack of panels at station 36, includes a vacuum table 164 for positioning the sheets for transfer to the stack, a wand 166 for delivering the sheets from the table to the stack, and a supply unit 168 for feeding paper to the table. As in conventional panel-packaging operations, the sheets of paper thus interleaved between the panels in the stack are at least about as long and as wide as the panels, to afford ensured full protection of the painted panel surfaces against abrasion.

The vacuum table 164, best seen in FIGS. 16-19, comprises an elongated metal vacuum box or platen 170 having a flat, rectangular, perforated upper surface 172 that is both longer and wider than the sheets of paper to be interleaved. Suitable frame structure 173 fixedly supports the platen 170 in a position above and to the right of the stacking station 36 (as seen in FIGS. 3, 4 and 16), with the long dimension of surface 172 ex-

tending in parallel relation to the long dimension of panels stacked at station 36, and with surface 172 inclined laterally toward the stacking station. Means such as a reversible blower 174, secured to the platen and communicating with the interior thereof through a portion 174a, are provided for alternately evacuating and blowing air into the hollow platen interior, thereby to create suction or an air blast through the perforations 175 of surface 172.

10 A plurality of endless belts 176 extend, in spaced parallel relation to each other, across surface 172 (in the direction of the long dimension thereof) between drive rollers 178 and idler rollers 180 respectively journaled in opposite end portions 181 and 182 of the platen 172. These belts are adapted to be driven, through drive means 184 connected to rollers 178, in a direction parallel to the long dimension of surface 172, with the upper runs of the belts advancing away from the platen end portion 181 across the surface 170.

15 A set of feed rollers 186, for advancing a continuous web 187 of paper longitudinally onto the surface 172 of platen 170, is mounted at the end 181 of the platen in axially parallel relation to the rollers 178 and is driven by the drive means 184 through a belt 188. A paper-cutting knife 190 (FIGS. 19 and 20) is pivotally mounted at one side of the platen 170 for movement across the width of the path of the advancing web 187, i.e. in a plane transverse to the direction of paper feed adjacent the feed rollers 186 at platen end 181, to cut the web transversely into sheets of desired length. The knife is operated by a hydraulic or pneumatic mechanism 192 supported by the frame structure 173 and having a piston 194 connected to the free end of the knife.

20 30 35 The web 187 is supplied to rollers 186 by the unit 168 (FIGS. 21 and 22), which includes a mount 196 rotatably supporting a roll 198 of paper of the requisite width for the interleaving sheets, and a motor 199 for rotating the roll 198 to unwind the web 187. From the roll, the web is directed around rollers 200 and 201 to the top of a vertical frame 202 which guides an axially horizontal dancer roller 204 for sliding vertical movement. The web passes under and around the dancer roller 204, so as to support that roller, and is then guided around an axially inclined roller 206 at the top of frame 202, from which it passes to the feed rollers 186 for advance onto the vacuum table 164.

40 45 50 55 60 65 As will be understood, the vertical position of the dancer roller 204 in frame 202 changes in accordance with variations in the length of that portion of the web which extends between roll 198 and feed rollers 186; i.e. the dancer roller descends as the web is unreeled from roll 198, and rises as the web is pulled forward by the feed rollers. Operation of the motor 199 is controlled by a vertically spaced pair of photoelectric switches 208 and 210 positioned to scan preselected upper and lower localities in the path of vertical movement of the dancer roller 204. When the dancer roller rises above the upper switch 208, the switch responds to the sensed disappearance of the roller and web by actuating the motor 199 to feed paper from the roll 198. Such feed continues until the dancer roller 204 descends below the lower switch 210, which responds to the sensed presence of the dancer and web to arrest rotation of roll 198 by motor 199; the roll 198 then remains stationary until the dancer roller is raised again (by progressive advance of the web by the feed rollers

186) past the upper switch 208. In this way, the vertical travel of the dancer roller is controlled between upper and lower limits respectively represented by the positions of switches 208 and 210, as desired to maintain the web 187 under appropriate but not excessive tension during feed of paper from the roll 198 to the table 164.

For supply of an interleaving sheet 17 to the table 164, the feed rollers 186 and belts 176 are driven while the blower 174 is operated to continuously evacuate the interior of the platen 170 and thereby to create suction at the perforations 175 of surface 172. A strip of paper of the requisite width is delivered as a continuous web 187 from unit 168 to the table by the feed rollers, and is advanced longitudinally along the upper surface 172 of the platen (from end 181 toward end 182 thereof) by means of the driven belts 176 while being held against the platen and belts by the suction acting through the perforations 175.

A pair of photoelectric switches 212 and 214 are mounted on the platen above, and in position to scan, areas of the surface 172 successively traversed by the advancing paper, adjacent the platen end 182 remote from the feed rollers. These switches are adapted to respond to the change in brightness of the scanned surface resulting from presence of the paper thereon. Switch 212, which is first reached by the advancing paper, responds to the sensed presence of the paper by actuating the knife-operating mechanism 192 to cause the knife 190 to slice through the web 187 adjacent feed rollers 186, thereby cutting the advancing strip of paper on table 164 to a desired length e.g. equal to or slightly greater than the length of the panels 10 being stacked. The second switch 214 responds to the absence and presence of paper, respectively, by starting and stopping the drive means 184 to initiate and arrest paper-advancing drive of the rollers 186 and belts 176.

As will be understood, after the paper is cut by knife 190, it continues to advance on table 164 until its leading edge passes under the second switch 214, which then arrests the drive means 184 to half the belts 176; switch 212 has already stopped the feed rollers 186 by disengaging a clutch and operating a brake incorporated in the drive means. The sheet of paper 17, having a length determined by the location of switch 212 and a position determined by the location of switch 214, is now held stationary on the platen upper surface 172 by the continued suction applied through perforations 175 by the blower 174. The sheet position on the table is selected so that the leading transverse edge of the sheet is aligned with the corresponding edges of the panels being stacked at station 36, the long dimension of the sheet being parallel to that of the panels in the stack. As best seen in FIGS. 16 and 17, the two switches 212 and 214 are carried in support arms 216 and 218 slidably mounted in a track 220 secured to, and extending longitudinally of, the platen 170, to enable adjustment of the positions of these switches (along the length of the table) as may be desired to vary the length and/or location of sheets 17 on the table in accordance with the length and/or position of particular panels being stacked.

In this way, a long strip of sheet 17 of paper is disposed on the table 164 in proper position for transfer to a stack of panels 10 at station 36 by operation of the wand 166, now to be described. When the sheet is thus

transferred, the switch 214 detects the absence of paper in its scanning field and responds by actuating the drive means 184 to advance a new sheet of paper into position on the table, i.e. by engaging the clutch incorporated in the drive means. The leading end portion of the continuous web 187 from unit 168 already projects between the feed rollers 186, because the knife 190 cuts the web beyond the feed rollers; hence delivery of the new sheet to the table proceeds fully automatically.

The wand 166, best seen in FIGS. 10-13, is an elongated, rigid, straight hollow metal bar that extends in parallel relation to the longitudinal edges of sheets 17 on table 164 (and thus also in parallel relation to the longitudinal edges of the panels 10 stacked at station 36) for at least substantially the entire length of the sheets. The wand is supported on a pair of arms 222, which project transversely of the long dimension of the wand and are secured at their upper ends to a shaft 224 journaled, in axially parallel relation to the wand, in brackets 226 on the housing structure 104. Rotation of shaft 224 effects corresponding angular movement of the wand about the shaft axis (i.e. about an axis parallel to the long dimension of the wand) between an upper, rightward position 166a (as seen in FIG. 10) and a lower, leftward position 166b (also as seen in FIG. 10).

Specifically, in its upper position 166a, the wand 166 is disposed immediately above and in slightly spaced, parallel relation to the lower longitudinal edge portion of the laterally inclined platen upper surface 172. In its lower position 166b, the wand is disposed slightly above and to the left of the left-hand longitudinal edges of panels stacked at station 36, i.e. in parallel relation to those panel edges. The platen surface 172 lies in a plane substantially tangent to the arcuate path of wand movement at position 166a, to accommodate the movement of the wand while facilitating juxtaposition of the wand and the lower longitudinal edge portion of a sheet 17 of paper on the surface 172 and subsequent transfer of the sheet to the stack of panels by the wand.

Drive for effecting angular movement of the wand is taken from the driven sleeve 124a of the central transfer arm (FIG. 13) through a gear box 228 mounted on the side wall of housing 104 beneath shaft 224. A belt 230 connects a pulley 232 secured to sleeve 124a with another pulley 234 secured to an axially vertical shaft 236 that projects upwardly from the gear box. Rotation of shaft 236 is transmitted by right-angle gears (not shown) in the gear box to an axially horizontal shaft 238 that projects from opposite sides of the gear box and bears a pair of wheels 240 at its opposite ends. A pair of linkages 242, connected between shaft 224 and pivots 244 respectively eccentrically disposed on wheels 240, transmit angular motion from shaft 238 to shaft 224 and thus to wand 166.

Thus the wand 166, like the transfer arms 34, is angularly moved by the indexing drive 132. The transmission arrangement including gear box 228, wheels 240, and linkages 242 is such that each 180° of rotation of sleeve 124a and arms 34 (in either direction) produce one 360° revolution of wheels 240 and effects one complete cycle of angular movement of wand 166 from its upper position 166a to its lower position 166b and back to its upper position 166a. This wand motion is so synchronized with the swinging of the transfer arms 34 that

the wand reaches its lower position adjacent the stacking station 36 at a time when the arms 34 are displaced about 90° from their rest positions and are therefore clear of the stacking station; as the transfer arms 34 turn further, approaching the stacking station with a panel 10, the wand is withdrawing to its upper position and is therefore out of the way of the arms 34. In other words, the panel-delivering advance of the arms 34 to the stacking station alternates with the sheet-delivering advance of the wand 166 to the stacking station so that the arms 34 and the wand do not interfere with each other.

As shown in FIG. 18, the lower surface of the wand 166 (i.e. the surface facing platen surface 172, when the wand is in the upper position) has a plurality of perforations 245 distributed along the length of the wand. The interior of the wand is connected by flexible conduits 246 to a suitable blower device 248 (FIGS. 11 and 12) alternatively operable to provide suction, and an air blast, through the perforations 244. Specifically, blower 248 may be arranged to provide suction through a first port 248a and an air blast through a second, opposed port 248b, respectively connected to separate branches 246a and 246b of conduits 246; the two ports are respectively controlled by a pair of solenoid valves 249a and 249b operable to close and open the ports for alternate application of suction and air blast through the conduits 246 to the wand.

When a sheet of paper 17 is delivered to and positioned on the table 164, the lower longitudinal edge of the sheet passes between the upper position 166a of the wand and the subjacent platen surface 172. At this time, the suction valve 249a of blower device 248 is closed. For transfer of the positioned sheet 17 from table 164 to the stack of panels at station 36, the valve 249a of blower 248 is opened to create suction through the wand perforations 244 while the wand is at its upper position, and the blower 174 ceases to create suction through the platen perforations 175. The lower longitudinal edge of the sheet 17 on table 164 is thereby attracted to and held by the wand (as shown in FIG. 18), i.e. by virtue of the suction acting through perforations 244. At the same time, blower 174 is operated to produce an air blast through the platen perforations 175, lifting the sheet from the platen surface 172, and thereby fully releasing the sheet from the platen.

As the wand swings down to its lower position 166b, it carries the released sheet 17 with it, the edge of the sheet remaining adhered to the wand by the continuing application of suction through the perforations 244. Upon arrival of the wand at position 166b, the sheet 17 overlies the uppermost panel 10 on the stack at station 36. At this point, valve 249a closes and valve 249b opens so that suction from blower 248 through the wand is terminated and an air blast is produced by the blower perforations 244, positively releasing the sheet 17, which is thus deposited on the panel stack. The wand returns to its upper position, with the valve 249b (controlling air blast from blower 248) again closed. In the meantime, blower 174 has resumed application of suction through the perforation platen surface 172, and switch 214 (responding to the disappearance of the sheet 17) has initiated advance of a new sheet 17 onto the table 164, in preparation for the next sheet transfer cycle.

Each cycle of the described operation of the wand 166, table 164, and blowers 174 and 248, automatically

deposits a properly dimensioned protective interleaving sheet of paper 17 in appropriate position on the upwardly facing surface of the topmost panel 10 on the stack at station 36. The next panel delivered to the stack by the transfer arms 34 will thus be positioned on top of the sheet of paper, i.e. separated by that sheet from the immediately subjacent panel in the stack. In each such cycle, the described sequence of suction and airblast applications effectuates delivery of the sheet to the stack in a fully automatic operation yet without tearing or misalignment of the sheet, or fouling of the apparatus by the sheet. For best results, it is preferred to use a paper (such as newsprint) that is relatively free of any tendency to become adhered by static electricity to adjacent portions of the apparatus.

The operation of the blowers 174 and 248 is synchronically controlled by the aforementioned control system (hereinafter described) in response to movement of the transfer arms 34, to provide a predetermined interleaving pattern. In one example of wand and blower operation, the described blower cycles are performed with each downstroke of the wand 166, to deliver a sheet of paper 17 to the stack at station 36 after each successive panel 10 is placed thereon. In another example (i.e. to provide the interleaving sequence described above with reference to FIG. 2), a sheet of paper is transferred to the stack only after every second panel is added to the stack. For the latter operation, the blowers are operated to cause the wand to pick up a sheet 17a from the table 164 after the first panel 10a is deposited at station 36. As the wand returns to its upper position, the indexing movement of arms 34 delivers a second panel 10b to the stack, and a second sheet 17b comes into position on table 164 for transfer to the stack.

The succeeding indexing movement of arms 34 (which will transfer a third panel 10c to the stack) is accompanied by a second downstroke of the wand; but the blower 248 does not apply suction through the wand perforations before this downstroke, and the blower 174 continues to apply suction through the platen perforations. Consequently, the sheet 17b remains on table 164, and the second downstroke of the wand is an idle downstroke. Switch 214, continuing to sense presence of sheet 17b on the table 164, does not initiate advance of another sheet.

The return of the wand from the second (idle) downstroke is accompanied by delivery of the third panel 10c to the stack. Now the paper-transferring cycle of blower operation is initiated again, so that the succeeding downstroke of the wand will place the second sheet 17b on top of panel 10c on the stack, and a further sheet 17c will be delivered to the vacuum table.

In other words, each panel-delivering indexing movement of the transfer arms 34 is accompanied by a downstroke of the wand 166; but the wand delivers an interleaving sheet, and a fresh sheet is advanced to the table 164, only if blower 176, and the valves 249a and 249b of blower 248, are actuated to cause the wand to pick up a sheet from table 164 at the start of such downstroke. Thus, interleaving of paper with alternate panels in the stack (as shown in FIG. 2), or other desired interleaving sequences, may be achieved by appropriately presetting the control system which governs operation of the blowers in accordance with successive cycles of operation of the transfer arms.

The operation of the apparatus thus far described, including the inverting, positioning, transfer and interleaving assemblies, is effective to build up automatically (on the platform at stacking station 36) a stack of panels 10 of desired number (e.g. 24) in a desired stacking and interleaving pattern such as that shown in FIG. 2. The portions of the apparatus 18 remaining to be described handle transfer of a completed stack to a carbon blank, and packaging of the stack in the carton blank.

STACK TRANSFER ASSEMBLY

As best seen in FIGS. 16 and 23-27, the frame structure 50 of the apparatus 18 includes a pair of horizontal members 250 extending in the direction of advance of the panels along opposite sides of the apparatus from the conveyor 22 past the stacking station 36 to the conveyor 24, substantially below the level at which panels are stacked at the stacking station. Adjacent the stacking station, each of the members 250 is supported by uprights 252 and 253. A pair of transverse horizontal frame members 254 extend across the width of the apparatus, on opposite sides of the stacking station and in parallel relation to the longitudinal orientation of the panels there stacked, at a level above members 250; these members 254 are secured at their ends to the aforementioned uprights 252 and 253. A further transverse frame member 255 is secured to and extends between the members 250 beneath the stacking station, intermediate and parallel to the members 254. The outlet conveyor 24 is supported on the members 250 at a location below and to the right of the stacking station 36 as seen in FIGS. 3, 4 and 16, and extends in parallel relation to the longitudinal orientation of the panels at the stacking station.

The stack transfer assembly, also shown in FIGS. 16 and 23-27, is supported on the frame structure just described. It includes a row of flat, horizontal platens 260 spaced apart along the longitudinal center line of the stacking station 36 and individually mounted on hydraulic lift mechanisms 262 which are secured to the member 255. The lift mechanisms are arranged to effect simultaneous vertical movement of the platens 260 in a common plane between an upper position (broken line 260a in FIG. 16) in which they cooperatively constitute the platform for stacking of panels at station 36, and a lower position (shown in solid lines in FIG. 16) about on a level with the outlet conveyor 24.

A horizontal bar 264, extending from side to side of the apparatus 18 beneath and parallel to the members 254, is mounted on a pair of rails 266 (respectively supported by the two frame members 250) for sliding horizontal movement in a direction transverse to the long dimension of panels stacked at station 36, i.e. for movement between a first position (FIG. 16) in which bar 264 lies to the left of the stacking station, and a second position (FIG. 26) in which it lies to the right of the stacking station but leftwardly of the outlet conveyor 24. The bar 264 bears a plurality of rigid horizontal fingers 268 which project therefrom, to the right as seen in FIG. 16, in position to extend transversely beneath the stacking station 36 and in register with the spaces between adjacent platens 260 when the bar 264 is at its above-described first position.

Referring to FIG. 16, it will be seen that the fingers 268 lie in a plane slightly above the lower position of platens 260 and also slightly above the outlet conveyor

24, but substantially below the upper position 260a of the platens. If the bar 264 is in its first position and the platens 260 are in their upper position, bearing a stack of panels 10, descent of the platens to their lower position transfers the stack to the fingers 268; i.e. as the platens descend between the fingers, the stack of panels is deposited on the fingers. The bar 264 may then be moved rightwardly to its second position, passing above the lowered platens 260 and below the right-hand one of members 254. Such movement advances the stack of panels, carried on the fingers 268, to a locality immediately above and aligned with the outlet conveyor 24.

The described movement of bar 264 is effected by a hydraulic mechanism 270, including a fixed piston 270a and a cylinder 270b carried with the bar. A horizontal pusher bar 272 extends parallel to the bar 264 on the right-hand side thereof as seen in FIGS. 16 and 26, so as to lie between bar 264 and a stack of panels carried on fingers 268. This pusher bar 272 is mounted for lateral movement relative to bar 264 by a hydraulic mechanism 274 which is carried with the bar 264. The bar 272 moves rightwardly with bar 264 to the position shown in FIG. 26, adjacent the outlet conveyor 24. When the bar 264 is retracted again to the left by the mechanism 270, withdrawing the fingers 268 to the left, bar 272 is maintained in its rightward position by mechanism 274, as shown in FIG. 27; i.e. the mechanism 274 effects rightward movement of bar 272 relative to bar 264 in correspondence with the leftward movement of bar 264. Consequently the bar 272, being held effectively stationary adjacent the outlet conveyor, engages and retains the stack of panels against leftward movement with the fingers 268 so that as the fingers are withdrawn, the stack of panels is deposited on the outlet conveyor. Thereafter, the mechanism 274 retracts the bar 272 to its initial position adjacent the bar 264.

The stack transfer assembly further includes a plurality of short horizontal arms 276 disposed in a double row along the sides of stacking station 36, in register with the spaces between adjacent platens 260, and all individually mounted on vertical shafts 278 journaled in brackets 280 secured to the members 254. Arms 276 are swingable in a horizontal plane (immediately beneath the upper position 260a of platens 260 as seen in FIG. 16) between positions in which they extend parallel to the members 254 and positions in which they project transversely of the members 254 into the stacking station.

The arms 276 on each side of the stacking station are moved simultaneously from one of their two positions to the other by a hydraulic mechanism 282 mounted on the adjacent member 254 and connected by rod means 284 to all of the arms 276 in a row. When the plates 260 descend to their lower position for transfer of a first stack of panels to the fingers 268, mechanisms 282 swing the arms 276 into the transverse positions, in which the arms 276 provide a substitute platform on which a second stack of panels 10 may be built up at the stacking station. After the bar 264 has delivered the first stack to the outlet conveyor 24 and has returned with bar 272 to its initial leftward position shown in FIG. 16, the platens are raised again by mechanisms 262 to their upper positions in which they lift the accumulating second stack of panels from the arms 276 and thereafter support this second stack as it continues to

be built up. At this time, the mechanisms 282 swing the arms 276 back to positions parallel to members 254 to provide clearance for descent of the second stack of panels with platens 260 when the stack is completed and ready for transfer to the fingers 268.

Vertical downward movement of the platens 260 is actuated by the aforementioned control system (hereinafter described) in response to delivery of a predetermined number of panels to the stack. The movement of arms 276, the movements of bars 264 and 272 which deposit the stack on the outlet conveyor, and re-elevation of the platens to their upper position (together with return of arms 276 to positions parallel to members 254) are effected in automatic sequence following the descent of the platens. In this sequence of operations, continuity of stacking proceeds uninterrupted owing to the function of arms 276 in providing a substitute stacking platform upon descent of the platens 260 with a completed stack.

PACKAGING ASSEMBLY

The outlet conveyor 24 (FIGS. 16, 25 and 28) comprises a pair of parallel endless belts 286 respectively disposed for movement above and within a pair of parallel, hollow support members 288 mounted on frame members 250. The belts, driven through drive rollers 290 journaled in members 288, are so arranged that their upper runs advance along the upper surfaces of members 288 in a direction (indicated by arrow 291, FIG. 28) parallel to the longitudinal orientation of panels at the stacking station 36.

An overhead conveyor 292 (FIG. 28) delivers elongated corrugated cardboard carton blanks 293 to the conveyor 24 from a stack 294 of such blanks disposed behind, and in alignment with, the conveyor 24. The conveyor 292 comprises a frame 296 translatable (by a suitable drive mechanism, not shown) along a fixed overhead horizontal track 298 between a position above stack 294 and a position above conveyor 24. A plate 300, suspended from frame 296 by vertical shafts 302 and vertically movable relative to frame 296 by a lift mechanism 304 carried on frame 296, bears on its lower surface one or a plurality of suction devices 306 to which suction may be applied through suitable conduits, not shown.

The blanks 293 are shaped and dimensioned to enclose a stack of panels 10 as built up at station 36. In operation, the frame 296 of conveyor 292 is initially moved to a position above the stack 294 and plate 300 is lowered for engagement of the suction devices 306 with the uppermost carton blank on the stack. Suction is applied to the devices 306 and plate 300 is raised, lifting the carton blank with it. The frame 296 is then moved to a position above the conveyor 24; plate 300 is lowered again, and suction is removed from devices 306 so that the carton blank is released therefrom and deposited on the conveyor 24. Frame 296 is then returned to its position above the stack 294 of carton blanks.

A carton blank 293 is thus delivered to the conveyor 24 prior to delivery of a stack of panels to the conveyor. The blank is so positioned on the conveyor 24 that the stack of panels 10 deposited by fingers 268 will rest on the blank on the conveyor in appropriate position for packaging. After the stack of panels is deposited on the blank, a plurality of powered, jointed arms 25 mounted along the side of conveyor 24 fold the pre-

scored longitudinal sides of the carton blank around and over the stack of panels. The arms 25, and the mechanism (not shown) for operating them, may be of a type that is conventional for folding such carton blanks, and accordingly they need not be described in detail.

From the time of deposit of the carton blank on the conveyor 24 until the completion of the folding operation by the arms 25, the belts 286 are stationary. Once the folding has been completed, the belts are driven to advance the packaged stack of panels within the folded carton blank in the direction of arrow 291 (FIG. 28) to down-line stations (not shown) for completing the closure and sealing of the carton. Subsequently the belts are halted and another carton blank is delivered to the conveyor 24 by the conveyor 292, in time to receive the next stack of panels 10 delivered by fingers 268.

The foregoing sequence of operations of the packaging assembly is performed automatically under control of 20 suitably arranged limit switches and other control instrumentalities (not shown). Specifically, arms 25 are actuated to fold the carton blank in response to completion of the operation of depositing a stack of panels on the carton blank. The conveyor belts 286 are driven, 25 to discharge the packaged stack from the apparatus, in response to completion of the folding operation by the arms 25. The belts 286 are halted after a predetermined extent of advance, and the delivery of a new carton blank is initiated in appropriate sequential relation 30 to the halting of the belts.

CONTROL SYSTEM

FIGS. 29a-29e together constitute a simplified schematic diagram of the control system for the apparatus of FIGS. 3 and 4, omitting for simplicity the controls for portions of the packaging assembly.

The system includes manual control switches (SW), and once these switches have been appropriately actuated, it operates fully automatically under control of a plurality of limit switches (LS) which are incorporated in the system, to provide the desired sequence of inverting, positioning, transferring, interleaving and other functions described above.

The manual control switches, conveniently arranged 45 on a control panel (not shown), are as follows:

Master control switch 1SW, comprising a start push button 2PB and a stop push button 1PB, turns all control circuits on and off. Buttons 2PB must be depressed before the other switches can be operated to initiate 50 operation of the apparatus. Depression of button 1PB completely stops operation of the apparatus.

Switch 2SW starts and stops the main hydraulic motor MTR1 which drives the conveyor 22, conveyor belts 176, and other elements of the apparatus. It has 55 two positions (off-on). It is turned on after depression of button 2PB.

Switch 3SW starts and stops the indexing motors MTR 2, MTR 3, and MTR 4, which respectively provide rotary indexing of the transfer arms 34, vertical movement of the transfer arms, and indexing of the inverter arms 70. Also an off-on switch, it is turned on after depression of button 2PB.

Switch 4SW energizes the control circuits for the inverter assembly 30. It has three positions: off, 1-1, and 60 2-2. When 4SW is in the 1-1 position, every alternate panel 10 advancing on conveyor 22 is inverted; i.e. the first, third, and fifth panels, etc., are inverted, while the

second, fourth, and sixth panels, etc., are not. When 4SW is in the 2-2 position, alternate pairs of panels are inverted; i.e. the first two are inverted, the next two are not, the following two panels are inverted, and so forth. This switch is turned on to the position corresponding to the desired inversion sequence.

Switch 5SW is an on-off switch that energizes the control circuits for the transfer arms, the interleaving assembly, and the indexing of the stop members 80. It is turned on for operation of those portions of the apparatus.

Switch 6SW is an on-off switch governing the time at which a panel is released at the stacking station by the pickup heads 141 at one end of the transfer arms (hereinafter termed the No. 1 heads), i.e. the three heads which simultaneously engage one panel. When 6SW is on, each panel transferred by the No. 1 heads is released at station 36 after the transfer arms have been lowered to their lowermost positions at the completion of the indexing cycle which carries the No. 1 heads to the transfer station. When 6SW is off, the panel is released during such descent of the transfer arms. The switch may be off or on during operation of the apparatus, to provide early or delayed release of panels from the No. 1 heads as desired.

Switch 7SW is identical to switch 6SW but controls the time of release of panels from the No. 2 heads of the transfer arms, i.e. the heads 141 at the opposite end of the arms from the No. 1 heads. As will be appreciated, when all the No. 1 heads are at pick-up locality 28, all the No. 2 heads are at stacking station 36, and vice versa.

On-off switch 8SW controls application of vacuum and air blast through the interleaving wand 166 in synchronism with movement of the No. 1 heads so that the wand transfers a sheet of paper to the stack of panels at station 36 each time the No. 1 heads are indexed from locality 28 to station 36. Switch 9SW is similar to switch 8SW but is synchronized with movement of the No. 2 heads. One or both of these switches are on during operation of the apparatus, to provide a desired interleaving sequence. For example, if only switch 8SW (or only switch 9SW) is on, a sheet of paper 17 will be deposited on the stack of panels only after every second panel is deposited on the stack. If both switches are on, a sheet of paper is deposited on each successive panel delivered to the stack.

On-off switch 10SW governs energization of the control circuits for the stack transfer assembly 40, and is on during operation of the apparatus.

Push-button switch 11SW provides manual override operation of the stack transfer assembly when desired; i.e. when depressed, it initiates removal of a stack of panels from station 36 regardless of the number of panels that have been stacked.

Counter 12SW is set to count a selected number of panels (from 0 to 40) and to automatically initiate stacktransferring operation of the assembly 40 when that number of panels has been deposited in a stack at station 36.

Counter 13SW is set to count a selected number of panels (0-40) and to step down the platens 260, for clearance, upon deposit of that preselected number of panels at station 36.

The operations thus pre-set by the manual controls are performed automatically, as stated, through the agency of the limit switches (LS). Referring first to the

inverting assembly 30, 25LS and 26LS are positioned to be tripped when the member 64 and heads 68 reach their uppermost and lowermost positions, respectively (FIG. 8). 27LS is disposed to be tripped when an advancing panel 10 arrives at the locality 57 of the raised heads, while 28LS is tripped upon return of the panel to the conveyor 22 after inversion (FIG. 7). 29LS is tripped when the arm 70 returns to its rest position, and 30LS is tripped when the arm has been indexed 180° forwardly from that position (FIG. 8).

It will be understood that in structure these limit switches, and those hereinafter described, may be generally conventional, and that they are equipped with sensors or trip elements of appropriate character and disposition to be actuated (for closing or opening the switch) by the specified event that is to trip the switch as will be apparent to those skilled in the art. For example, the switches which sense passage or position of a panel 10 on conveyor 22 may include whisker-type trip elements positioned in the path of panel advance. It will further be understood that the limit switch positions indicated on the apparatus drawings are merely exemplary, and are intended merely to illustrate one position in which each such switch could be mounted on the apparatus for operation as described.

For control of the transfer arms 34 and associated elements, 1LS (FIG. 6) is positioned to be tripped by a panel 10 arriving at the pick-up locality 28 on conveyor 22, while 1ALS is tripped by a panel arrested by the stop members 80 (FIG. 5), and 18LS, normally closed, is released by arrival of a panel at the arrested position (FIG. 5). 2LS is tripped when the transfer arms are raised to their upper position, and 3LS is tripped when the arms are lowered to their lower position (FIG. 13). 4LS is tripped when the No. 1 heads are rotated into pick-up position at locality 28; rotation of the No. 2 heads into the pick-up position trips 5LS (FIG. 13).

In the control circuits for the interleaving assembly 38, 31LS and 32LS are respectively tripped by the response of the photoelectric sensors 212 and 214 described above (FIG. 17). 33LS is tripped when the knife 190 descends to its lower position, while 34LS is tripped when the knife is raised to its upper position (FIG. 20). 36LS is tripped by arrival of wand 166 at its paper-discharging position above the stacking station 36 (FIG. 10).

The stack transfer assembly control circuitry includes 6LS, tripped by descent of platens 260 to their lower position (FIG. 16); 7LS, tripped by retraction of the pusher bar 272 to its leftward position relative to bar 264 (FIG. 25); 8LS, tripped by retraction of bar 264 to its first or leftward position (FIG. 26); 9LS, tripped by arrival of bar 264 at its second or rightward position (FIG. 26); 10 LS, tripped when the pusher bar is extended rightwardly relative to bar 264; 10 ALS, tripped by arrival of pusher bar 272 at its limiting position; and 13LS, tripped by partial descent of platens 260. 11LS, 12LS, 14LS, 15LS, 15ALS, 15BLS, and 16LS are tripped by successive movements of the hinged arms 25 in folding a carton blank on conveyor 24 and returning to their rest positions. 17LS is tripped by rotation of arms 276 to their stack-supporting positions (FIG. 23). 19LS is tripped by arrival of platens 260 at their upper positions 260a (FIG. 23). 20LS is tripped by arrival of a carton blank in stack-receiving position on conveyor 24, and is released by discharge of the folded carton from the conveyor (FIG. 280).

The various parts of the apparatus are operated by solenoids (SOL) under control of the above-described manual and limit switches. For the inverting assembly, 22SOL raises the heads 68 when energized, and lowers them when de-energized. 23SOL, when energized, causes indexing of the arms 70.

31SOL operates the inlet conveyor when energized and halts it when de-energized. 6ASOL causes indexing of the stop members when energized. 30SOL causes head 94 to effect alignment of a panel at locality 28.

1SOL and 2SOL respectively raise the No. 1 and No. 2 heads of the transfer arms 34 when energized, while 5SOL and 6SOL respectively apply suction to the cups 144 of the No. 1 and No. 2 heads when energized. 3SOL effects vertical movement of the transfer arms when energized, and 4SOL effects rotary indexing of the transfer arms when energized.

In the interleaving assembly, 24ASOL turns the paper control air on. 24 SOL and 25SOL respectively apply suction and air blast through the wand 166 when energized. 26SOL effects downward cutting movement of knife 190 when energized. 27SOL causes paper to advance on table 164 when energized, while energization of 28SOL effects engagement of the clutch and release of the brake incorporated in the paperadvancing drive 184.

In the stack transfer assembly, 7SOL moves arms 276 to stack-supporting position when energized, 8SOL (a DC solenoid) advances and retracts the bar 264 between its two positions, 10ASOL and 10BSOL respectively raise and lower the platens 260 when energized, and 11SOL extends pusher bar 272 when energized. 12SOL, 13SOL and 14SOL respectively effect successive carton-folding movements of the hinged arms 25 when energized, and 15SOL operates conveyor 24 when energized.

Energization and de-energization of the solenoids by the aforementioned manual and limit switches, to provide the desired sequence of operations in stacking and packaging of panels, is achieved by means of control relays (CR) and time-delay relays (TR), e.g. of individually conventional character, appropriately connected in the control system. These relays are conventionally represented in the circuits of FIGS. 29a-29e, together with their contacts, which are represented in conventional manner as normally open and normally closed, i.e. in accordance with their condition when the apparatus is not operating and the control circuits are not energized. Thus, normally open contacts are represented by parallel lines having an unbridged gap between them, while normally closed contacts are shown with the gap bridged by a diagonal line. In the illustrated circuits, bus lines are designated by the letter L, as 2L, 4L, 34L, etc.

The arrangement of the control circuits, and the way in which the various relays operate (in conjunction with the switches) to provide the desired control function already described, will be apparent to one skilled in the art from an examination of FIGS. 29a-29e. Nevertheless, by way of illustration, a partial explanation of the detailed operation of the control circuits including these relays will now be set forth.

Referring then first to FIG. 29a, the four motors MTR 1, MTR 2, MTR 3 and MTR 4 are powered from a 460-volt, 3-phase, 60-cycle current supply which also provides 110-volt current for the control circuit through a transformer TSF.

Depression of the master start button 2PB energizes CRM having normally open self-locking contacts in parallel with 2PB to provide continuing current flow through the control circuits after release of 2PB, i.e. until the master stop button 1PB is depressed.

After 2PB is depressed, relay 1M is energized by turning 2SW on, to close normally open contacts of 1M and thus to start the hydraulic motor MTR 1. By turning switch 3SW on, relay 2M is energized to close normally open contacts thereof for starting the motors MTR 2, MTR 3, and MTR 4.

When switch 4SW is turned to either the 1-1 or the 2-2 position, the control circuitry for the inverting assembly 30 is energized and conveyor 22 begins to run; 15 additional controls (not shown) may be provided to adjust the conveyor speed as desired. When switch 5SW is turned on, the control circuits for the transfer arms 34 and interleaving assembly are energized and the belts 176 begin to run, bringing a first sheet of paper into position on table 164. The stack transfer control circuits are energized by turning 10SW on.

Referring to FIG. 29b, the heads 68 of the inverting assembly are elevated to their raised positions upon turning 4SW to either the 1-1 or the 2-2 position, because 23SOL is energized through normally closed contacts of 30CR. If it is desired not to invert the first panel 10 advancing on conveyor 22, i.e. for the stacking pattern shown in FIG. 2, the inverting assembly is cycled once (with 4SW at 1-1 position) before the first panel is advanced. However, for simplicity, the panel-inverting control circuitry may be described as operated for invention of the first panel.

Since the heads 68 are raised upon turning 4SW to 1-1 position, 25LS is tripped, as in 29LS, the arms 79 being initially at rest position. 30LS is at its illustrated position. Arrival of a panel at the heads 68, by tripping 27LS, now energizes 121CR and 22SOL, causing the arms 70 to be indexed so as to invert the panel and return it to the conveyor 22 beyond heads 68. Thereupon 28LS is tripped, and the condition of 30LS is reversed; 27LS and 29LS are opened, with the result that 122CR and 30CR are energized, opening the normally closed contacts of 30CR between 4L and 23SOL, but the heads 68 remain up because 23SOL continues to be energized through contacts of 29CR. Return indexing of the arms 70 by 22SOL to rest position restores the initial configuration of 30LS and trips 29LS, opening the normally closed contacts thereof between 4L and 23SOL; since 30CR has self-locking contacts it remains energized although 122CR is now deenergized, and hence 23SOL is de-energized, causing the heads 68 to move to their lower position and tripping 26LS.

The second advancing panel is not inverted, but it does trip 27LS, energizing 27CR and thereby energizing 2TR (because 26LS is now closed). The arms 70 do not index, as 25LS is open and 30CR is energized. Passage of the second panel beyond locality 57 re-opens 27LS but 2TR remains energized through self-locking contacts. Shortly thereafter, time-delay contacts of 2TR open to de-energize 30CR, thereupon reclosing contacts of 30CR through which 23SOL is energized. The heads 68 are now raised again to repeat the inversion cycle for the third advancing panel.

If 4SW is turned to the 2-2 position, 23SOL is again initially energized through the normally closed contacts of 30CR raising the heads 68 to panel-inverting position. 29LS is closed and 29CR is energized because the

arm **70** is at rest position. **25LS** is also closed, because the heads are up. Arrival of a panel **10** at the locality of the heads on a conveyor **22** trips **27LS**, energizing **27CR** and thereby closing contacts to energize **121CR**, with the result that **22SOL** is energized to index the arms **70** and invert this first panel.

Upon completion of the forward indexing movement of the arms, **30LS** is tripped (i.e. its illustrated normal condition is reversed), and **28LS** is tripped, while **29LS** and **27LS** are opened. **121CR** is de-energized, and immediately thereafter **122CR** thus becomes energized, and **SCR** is also energized through now-closed contacts of **122CR**. **YCR** and **30CR**, however, do not become energized.

At the completion of return indexing of the arms **70**, **30LS** has returned to normal condition and **29LS** is closed, de-energizing **122CR**, but **23SOL** remains energized (and hence the heads remain raised) because **30CR** has not yet been energized. However, **SCR** remains energized through self-locking contacts after de-energization of **122CR**.

Arrival of the second panel at the heads, again closing **27LS**, re-energizes **121CR** and thereby again energizes **22SOL** to index the arms **70** for inversion of the second panel. At this time, **YCR** becomes energized through the now closed contacts of **XCR** and **121CR** and remains energized through self-locking contacts after de-energization of **121CR**. The second energization of **122CR** (i.e. upon completion of forward indexing of the arms inverting the second panel) consequently energizes **30CR** through the closed contacts of **2TR** and the now closed contacts of **YCR**. Return indexing of the arms deenergizes **122CR**, but **30CR** remains energized through its self-locking contacts so that when the return of the arms **70** to the rest position trips **29LS**, **23SOL** is de-energized, causing the heads **68** to descend to their lower position, i.e. after two successive panels have been inverted.

The descent of the heads closes **26LS**. The next (third) advancing panel is not inverted, but trips **27LS** transiently as it advances on conveyor **22**, energizing **27CR** and thereby energizing **ECR** and **FCR**. After the passage of the third panel reopens **27LS**, **ECR** and **FCR** remain energized through selflocking contacts.

Since the switch **4SW** is in the **2-2** position, the only path for initial energization of **2TR** is through the seriesconnected **26LS**, **FCR** contacts and **27CR** contacts. There is, however, a sufficient delay in closure of the last-mentioned **FCR** contacts so that **27CR** has reopened before these **FCR** contacts close. Accordingly **2TR** is not yet energized, and **30CR** remains energized, so that the heads **68** remain in their lower position. Once closed, however, the last-mentioned **FCR** contacts remain closed because **FCR** remains energized.

Thus when the fourth panel, advancing on conveyor **22**, trips **27LS**, **2TR** becomes energized and remains so through self-locking contacts after **27CR** is de-energized by the advance of the panel beyond **27LS**. This fourth panel, again, is not inverted, because the heads are still down. However, shortly after passage of the fourth panel, the time delay contacts of **2TR** open, de-energizing **30CR** and thereby reenergizing **23SOL** to raise the heads once more to inverting position, i.e. for inverting the fifth and sixth panels. **26LS** is thus opened, **25LS** is closed, and the entire cycle is repeated.

Also in FIG. **29b**, **31SOL** which governs the running of conveyor **22** is energized through normally closed **18LS**. Arrival of a panel in arrested position at the pick-up locality **28** trips **18LS** open to de-energize **31SOL** and temporarily halt the belts of conveyor **22** until the panel is picked up, so as to avoid abrasion of the panel by the belts. As soon as the panel is picked up, **18LS** recloses and **31SOL** is re-energized to resume drive of the conveyor.

FIG. **29c** illustrates the control circuits for the transfer arms. When **5SW** is turned on, with the transfer arms **34** at their upper position and the No. **1** heads **141** at pick-up position (i.e. above pick-up locality **28**), **2LS** is closed (i.e. it is in the reverse of the condition illustrated) and **4LS** is closed so that **4CR** is energized. When a panel advancing on conveyor **22** arrives at the pick-up locality, it trips **1LS** (FIG. **29a**) to energize **PCR**. **1CR** is thereby energized, assuming, for example that **19LS** (tripped by the platens **260** in their upper position) is closed. Referring to the energizing circuit of **1CR**, it may be noted that the illustrated arrangement of relay contacts **CTCR**, **107CR**, and **2CTCR** and **19LS** is designed to permit energization of **1CR** whenever the panel stacking station **36** is in condition to receive panels but not otherwise. The last-mentioned relays are shown in FIG. **29e**.

Energization of **1CR** causes energization of **103CR**, **105CR**, and **106CR** and also energizes **3SOL** to initiate the indexing cycle for vertical movement of the transfer arms. Thereupon the transfer arms descend to their lower position switching the condition of **2LS** to that illustrated and closing **3LS** to energize **3CR**. **1CR** is thus de-energized while **101CR** is energized. **103CR** remains energized through its self-locking contacts and **2LS**. **105CR** remains energized also, but **106CR** is de-energized.

Lowering of the arms **34** brings the suction cups **144** of the No. **1** heads into contact with the panel at station **28**. Upon closure of a time delay contact of **105CR**, **5SOL** is energized to apply suction to these cups so that the No. **1** heads grip the panel.

Since **3SOL** remains energized (through **2LS** and contacts of **103CR**), the indexing cycle for vertical movement of the transfer arms continues, and at the end of a dwell time in the down position, the arms **34** are raised back to their upper position, again reversing the condition of **2LS** while opening **3LS** to de-energize **3CR**. This elevation of the arms **34** lifts the gripped panel from the pick-up locality, opening **1LS** to de-energize **PCR**. **101CR**, however, remains energized through its self-locking contacts and normally closed contacts of the de-energized relays **5CR** and **106CR**.

Since **2LS** has again been switched to the reverse of the condition illustrated by the elevation of the transfer arms, **2SOL** is now energized through the normally closed contacts of de-energized relays **106CR** to elevate the No. **2** heads to their upper position; but since **105CR** is energized, **1SOL** remains de-energized and the No. **1** heads (carrying the panel) remain in their lower position.

The described tripping of **2LS** by elevation of the arms also energizes **4SOL** which effects rotary indexing of the transfer arms through 180° . At the same time, **6ASOL** is energized to index the stop members **80** through 90° .

As the No. **1** heads leave the pick-up locality, **4LS** opens and **4CR** is de-energized. Arrival of the No. **2**

heads at the pick-up locality upon completion of the 180° indexing movement of the transfer arms trips 5LS to energize 5CR. 105CR, however, remains energized through the normally closed contacts of de-energized relay 3CR.

Energization of 5CR de-energizes 101CR and thereby de-energizes 2SOL, causing the No. 2 heads to descend to their lower position.

Arrival of the next panel at the pick-up locality 28 again trips 1LS, energizing PCR and thereby energizing 1CR, 105CR, 106CR and 3SOL, which moves the transfer arms back down to their lower position. A time delay contact of 106CR opens to de-energize 5SOL (assuming that 6SW is off), removing suction from the cups of the No. 1 heads and releasing the gripped panel for deposit on the stack at station 36. This operation of the time delay contacts of 106CR is timed to occur during descent of the transfer arms following completion of the rotary indexing step. If 6SW is turned on, 5SOL is not de-energized (and hence the suction is not removed) until the descent of the arms is completed, tripping 3LS, energizing 3CR, and thereby de-energizing 105CR.

The cycle is then repeated for pick-up of the second panel by the number 2 heads through operation of the relays associated therewith in the same manner as described above with reference to the No. 1 heads.

As each panel arrives at arrested position at the pick-up locality 28, it also trips 1ALS, i.e. prior to energization of 103CR. Thereby, 30SOL is energized to actuate the head 94 for engagement with the end of the panel to align the panel properly. The energization of 103CR de-energises 30SOL to effect retraction of the head 94.

The control system for the interleaving assembly is shown in FIG. 29d. At the start of operation, with no paper on table 164 and the knife 190 in the up position. 32LS is in the condition shown and 34LS is tripped. 27SOL and 28SOL are thus energized, for advancing the web of paper longitudinally over the table.

Arrival of the leading edge of the web beneath photo-electric sensor 212 trips 31LS, energizing 26SOL to move the knife for cutting the web. As the knife reaches the lower end of its stroke, it trips 33LS to energize 127CR (which then remains energized through self-locking contacts), de-energizing 26SOL so that the knife rises again to its up position, and also de-energizing 28SOL to disengage the clutch and actuate the brake of the web-feeding drive.

The opening of 34LS upon descent of the knife momentarily de-energizes 27SOL, but with energization of 127CR, advance of the cut sheet of paper along the table is resumed until the leading edge of the sheet arrives beneath photo-electric sensor 214, tripping 32LS. As 32LS is thereby reversed from the condition illustrated, 127CR and 27SOL are de-energized and advance of the paper is halted.

The tripping of 32LS just described, representing arrival of a sheet of paper on the table 164 in position for transfer by the wand 166, energizes the circuits controlling application of suction and air blast through the wand. If 8SW is on, arrival of the No. 1 heads of the transfer arms 34 at the pick-up locality 28 (energizing 4CR, FIG. 29c) energizes 3TR. Consequently, 124CR is energized, and so is 24SOL, which applies suction through the wand 166 for picking up the sheet from the table 164. The wand, at this time, is at its upper posi-

tion. However, the continuing application of suction to the table holds the sheet of paper thereon.

Tripping of 2LS upon elevation of the transfer arms 34 energizes 24ASOL (FIG. 29c) to apply an air blast through table 164, releasing the paper from the table. Synchronously with rotary indexing of the arms 34, the wand swings to its lower position, tripping 36LS open. 24SOL is de-energized, terminating suction through the wand, and energization of 25SOL applies an air blast through the wand to detach the paper therefrom for deposit on the stack at station 36. 24ASOL is also de-energized at this time, restoring application of suction through the table 164.

As the wand swings back to its upper position, the absence of paper on the table 164 reverse-trips 32LS back to its starting condition, for renewed feed of paper to the table. If 9SW is on, the paper-delivering cycle of suction and air blast will be repeated upon indexing of the No. 2 heads 141 from the pick-up locality. On the other hand, if 9SW is off, this paper-delivering cycle will be performed only upon indexing of the No. 1 heads, and the wand will swing idly during indexing of the No. 2 heads, without lifting a sheet of paper from the table.

The control circuits for the stack transfer assembly are shown in FIG. 29e. When 10SW is turned on, the platens 260 are up, and bars 264 and 272 are in their first positions (to the left, as seen in FIG. 16). Thus 7LS, 8LS, and 19LS are tripped, i.e. in the reverse of their illustrated conditions, while 20LS is tripped as soon as a carton blank is deposited on conveyor 24. The counters 13SW and 12SW are preset for desired numbers of panels, and 1CTCR and 2CTCR are not energized. 10ASOL is thus energized, as is TCR.

The counters respond to successive closures of normally open contacts of 3CR (FIG. 29c) representing delivery of successive panels to the stack. When the step-down counter 13SW has thus counted a predetermined number of panels, it energizes 2CTCR and thereby de-energizes 10ASOL while energizing 10BSOL to initiate descent of the platens 260, reverse-tripping 19LS. When the platens are part-way down, 13LS is tripped, de-energizing 10BSOL to halt their further descent. After 12SW has counted the full number of panels desired for a complete stack, it energizes 1CTCR, thereby de-energizing TCR and consequently re-energizing 10BSOL to complete the descent of the platens.

When the platens reach their lowermost position, 6LS is tripped, and (assuming that a carton blank has been placed on conveyor 24, so that 20LS is tripped), 6CR is energized, with the result that 107CR and 7SOL are energized to swing arms 276 to their stack-supporting positions. Through contacts of 107CR, 7SOL remains energized (keeping the arms 276 in this position) until platens 260 return to their upper position, once again tripping 19LS, whereupon 7SOL is de-energized and arms 276 swing away from their stack-supporting positions.

Movement of arms 276 to stack-supporting position trips 17LS. At this time, 14LS, 15LS, 15ALS, 15BLS and 16LS are all closed, representing the rest positions of the carton-folding arms 25. 14CR and 8CR are thereby energized. Advance of the bar 264 and its associated fingers (bearing the completed stack of panels) to a position above conveyor 24 is now initiated by energization of 8SOL through a valve controller SV. This

advance of the bar 264 trips 9LS, energizing 0CR and concurrently de-energizing HCR, and opens 7LS; energization of 9CR closes contacts to energize 111CR, 113CR, 11SOL (which advances the pusher bar 272), and 12SOL, 13SOL and 14SOL (which operate the arms 25 to fold the stack of panels deposited on the carton blank). 14LS, 15LS, 15ALS, 15BLS, and 16LS now open, de-energizing 14CR. Meanwhile, bar 264 is retracted by 8SOL to its first position, reverse-tripping 9LS and closing 7LS.

Completion of pusher advance trips 10ALS, while operation of the arms 25 trips 11LS and 12LS. 15SOL is thus energized, operating the conveyor 24 to discharge the packaged stack of panels, and thereby re-opening 20LS. With 1CTCR and 2CTCR de-energized, full retraction of the pusher bar 272 (tripping 8LS) re-energizes 10ASOL to raise the platens 260 again to their upper position. The counters 12SW and 13SW are already counting the delivery of panels to the next stack.

If the manual override push-button switch 11SW is depressed during the stacking operation, it de-energizes 10ASOL and TCR, thereby energizing 10BSOL for immediate descent of the platens 260 to their lower position. This initiates the stack-transferring operation of bar 264 independently of the operation of counters 12SW and 13SW.

As will now be appreciated, the above-described apparatus 18 receives a succession of formed and finished siding panels, stacks them in superposed parallel relation to each other and in a desired sequence of laterally offset positions and inverted orientations relative to each other, interleaves the panels with protective sheets of paper in a desired sequence as stacking proceeds, deposits the completed stack of panels with interleaved paper on a carton blank, folds the blank to enclose the stack laterally, and discharges the thus-packaged stack, in a fully automatic operation. While the operation of the apparatus has been described with specific reference to the stacking pattern shown in FIG. 2, other patterns may be provided by the apparatus for panels of various different configurations as exemplified by the stacking patterns shown in FIGS. 30, 31, 32, 33 and 34. These figures also illustrate the positions of the suction cups 144 of the transfer arms 34 in relation to various different shapes of surfaces of panels 10. The desired stacking pattern is achieved by presetting the control system of the apparatus to provide a desired sequence of operations of the inverting assembly 30, and employing appropriately shaped cams 88 to control the indexing of the stop members 80.

It is to be understood that the invention is not limited to the features and embodiments hereinabove specifically set forth but may be carried out in other ways without departure from its spirit.

We claim:

1. In apparatus for stacking and packaging elongated panels, in combination,

- a. means for successively advancing a plurality of the panels transversely of their length along a defined path to a first locality;
- b. means for inverting a panel advancing along said path ahead of said first locality by turning the panel about an axis parallel to its length, said inverting means being selectively operable to invert only certain ones of successively advancing panels in accordance with a predetermined sequence;

c. means for arresting panels at said first locality at any one of a plurality of positions at which the panels are disposed at respectively different distances from a fixed line parallel to their length, the difference between any two of the aforesaid distances being less than the width of a panel, and said arresting means being operable to arrest successively advancing panels at respectively different ones of said positions in accordance with a predetermined sequence;

d. means for successively transferring arrested panels from said first locality to a second locality and depositing said panels in superposed parallel relation to each other at said second locality to build up a stack of the panels while maintaining each said panel in its orientation as arrested at said first locality, said panel-transferring means removing each successive panel from said first locality after arrest thereof by said arresting means and prior to advance of the next successive panel to said first locality, and advancing each panel the same predetermined fixed distance in a direction transverse to its length in transferring the panel from said first locality to said second locality such that the relative positions of successive panels on the stack are determined by the respective positions at which they are arrested at said first locality;

e. means for depositing an elongated sheet of flexible material on, and in substantial alignment with, a panel deposited at said second locality prior to delivery of the next successive panel to said second locality;

f. means for depositing, at a third locality, a carton blank shaped and dimensioned to be folded around a stack of the panels to laterally enclose the stack;

g. means for transferring a stack of panels from said second locality to said third locality and depositing the stack on a carton blank at said third locality in position to be laterally enclosed thereby as aforesaid; and

h. means for folding a carton blank laterally around a stack of panels at said third locality.

2. Apparatus as defined in claim 1, wherein said inverting means comprises

- i. means for engaging and turning a panel advancing in said path, and
- ii. means for actuating said engaging means to engage and turn a panel in response to the sensed passage of a predetermined number of panels along said path.

3. Apparatus as defined in claim 2, wherein said arresting means includes means for aligning the ends of successive panels along a common line at said first locality, said aligning means including means for engaging an end of a panel at said first locality and means for actuating said end-engaging means to engage and align a panel in response to the sensed presence of the panel at said first locality.

4. Apparatus as defined in claim 3, wherein said panel-transferring means comprises

- i. means for engaging and moving a panel from said first locality, and
- ii. means for actuating said last-mentioned means to engage and move a panel as aforesaid in response to the sensed presence of a panel in an arrested position at said first locality.

5. Apparatus as defined in claim 4, wherein said arresting means comprises

- i. stop means for engaging a panel to arrest the same at said first locality, said stop means being movable to engage and arrest a panel at each of said plural positions, and
- ii. means for moving said stop means from one to another of said positions in response to panel-moving operation of said panel-transferring means.

6. Apparatus as defined in claim 5, wherein said sheet-depositing means comprises

- i. means for holding a sheet of said flexible material in position for transfer to said second locality,
- ii. means for lifting a sheet from said holding means and delivering it to said second locality,
- iii. means for actuating said lifting means to lift and deliver a sheet as aforesaid in response to and in synchronism with panel-moving operation of said panel-transferring means such that the sheet is delivered to said second locality prior to deposit of a panel at said second locality, and
- iv. means for delivering a sheet of said flexible material to said holding means in response to removal of a previous sheet from said holding means by said lifting means.

7. Apparatus as defined in claim 6, wherein said last-mentioned actuating means actuates said lifting means in response to sensed performance of a predetermined number of panel-moving operations of said panel-transferring means.

8. Apparatus as defined in claim 7, wherein said stack-transferring means includes

- i. means providing a movable platform positionable to support a stack of panels at said second locality and displaceable for transfer of the stack therefrom;
- ii. means for displacing said platform from said second locality in response to deposit of a predetermined number of panels at said second locality;
- iii. means for lifting a stack of panels from said platform, upon displacement thereof as aforesaid, and delivering the stack to a carton blank at said third locality, and
- iv. means for supporting a stack of panels at said second locality, during displacement of said platform therefrom, in position for transfer to said platform upon return of said platform to said second locality.

9. Apparatus as defined in claim 8, wherein said carton-blank-folding means comprises a conveyor on which a carton blank is deposited as aforesaid at said third locality, arm means disposed adjacent said conveyor for engaging and folding side portions of said carton blank laterally around a stack of panels in response to completion of the stack-depositing operation of said stack-transferring means, and means for driving said conveyor to discharge a stack of panels enclosed in a carton blank from said third locality in response to completion of the blank-folding operation of said arm

means; said wherein said carton-blank-depositing means comprises means for advancing a carton blank to and depositing the blank on said conveyor in response to completion of the discharging operation of said conveyor-driving means.

10. Apparatus as defined in claim 1, wherein said stack-transferring means comprises

- i. A row of spaced-apart platens cooperatively providing a horizontal platform for supporting a stack of panels at a first level at said second locality;
- ii. means supporting said platens for simultaneous vertical movement between said first level and a second, substantially lower level, for lowering a completed stack of panels toward said second level;
- iii. means including a horizontal member and a plurality of rigid fingers extending therefrom transversely of said row of platens and in register with spaces between adjacent platens of said row at a level intermediate said first and second levels, said bar and fingers being horizontally translatable between a first position, vertically beneath said first level at said second locality, at which said fingers are disposed to receive a stack of panels from said platens during descent of said platens to said second level, and a second position at said third locality;
- iv. means for moving said bar and fingers to said second position in response to descent of said platens to said second level, for delivering to said third locality a stack of panels carried on said fingers, and for thereafter returning said bar and fingers to said first position;
- v. discharge means carried by said bar, and movable relative thereto, for pushing a stack of panels laterally off said fingers in synchronism with return of said bar from said second position, thereby to deposit the stack at said third locality;
- vi. means for actuating said platen-supporting means to lower said platens to said second level in response to deposit of a predetermined number of panels at said second locality, and to raise said platens to said first level in response to return of said bar and discharge means to said first position;
- vii. a plurality of arms movable into and out of a position for supporting a stack of panels at a level slightly below said first level at said second locality, said arms being in register with spaces between said platens, said arms providing a substitute platform for support of a stack of panels at said second locality when said platens are at said second level, said platens lifting the stack from the arms upon return of the platens to the first level; and
- viii. means for moving said arms into and out of panel-supporting position in response to descent of said platens to said second level and elevation of said platens to said first level, respectively.
